 Associated Electric Laboratories, Inc., Chicago,
 Ill., a corporation of Delaware

Application June 30, 1939, Serial No. 282,037

65 Claims. (Cl. 179—26)

The present invention relates to telephone systems and, more particularly, to improvements in the switching apparatus provided in small exchanges of the type adapted for use in rural communities or other areas including only a limited number of subscribers. In providing telephone facilities for the subscribers in an area of this character it is frequently desirable, from the standpoint of installation cost and maintenance, to equip the subscriber substations with ordinary manual type telephones, which may be of the local battery magneto type, and to provide automatic switching facilities in an exchange located in the area, the switches of which are controllable from a remote point, generally the central exchange of a distant city where operators are available at all times. The subscribers' lines may be of the single party or multiparty type, or both, and certain of the substations of the system may be of the paystation type. In certain instances it is also economically advantageous to utilize the remotely controlled community automatic exchange as a tandem exchange in setting up connections between the central exchange and a third exchange. Usually the apparatus provided in the remotely controlled community exchange comprises one or more finder-connector links, the connector portions of which are controllable from the central exchange over one or more trunk lines extending between the community exchange and the central exchange. In those cases where the traffic requirements are such that a plurality of links must be used, common equipment, including a link distributor, is usually provided for assigning the links to the use of calling ones of the lines terminating at the remotely controlled exchange.

It is an object of the present invention to provide improved switching apparatus of the character described which is of simple and economical arrangement and which may easily be controlled by an operator located at a distant point.

It is another object of the invention to provide an improved arrangement of the character described wherein the apparatus for transmitting incoming call signals and paystation identifying signals to the operator's position in the central exchange is partially included in the common equipment of the remotely controlled exchange, thus eliminating the necessity for complicated signal control apparatus in each of the finder-connector links provided in the latter exchange.

It is a further object of the invention to provide apparatus of the character described which is so arranged that the link distributor of the

common equipment is held operated until a call routed by way of an assigned link to the operator's position in the central exchange is answered, whereby calls originating on the lines terminating at the remotely controlled community exchange must be handled by the distant operator in the order of their initiation, and a single timing device incorporated in the common equipment may be used for initiating link substitution in the case when the finder portion of an assigned link fails to find the line to which it is assigned and also to release an assigned link in the case when a call routed to the distant operator's position is not answered within a predetermined time interval.

It is another object of the invention to provide improved apparatus of the character described which is so arranged that when a link in the remotely controlled exchange is seized by the operator in the central exchange a signal is transmitted to the operator only if the connector portion of the link is fully released.

It is another object of the invention to provide, in a telephone system of the character described, switching apparatus arranged in an improved manner such that a signal of one character is transmitted to the central exchange operator when a link in the remotely controlled exchange is seized provided the apparatus in the remotely controlled exchange is in proper working order, and a signal of different character is transmitted to the central exchange operator if a fault is present in the apparatus embodied in the remotely controlled exchange.

It is another object of the invention to provide, in an automatic telephone system, automatic switching apparatus which is arranged in an improved manner such that when a connection routed by way thereof is released, the apparatus through which the connection is routed is held operated for a time interval during which a busy signal is transmitted over the calling end of the connection.

It is a further object of the invention to provide, in an automatic telephone system, automatic switching apparatus which is arranged in an improved manner such that the ringing control apparatus provided in the connector switch through which a connection is routed is directly controlled by the calling device located at the calling end of the connection, whereby code ringing may be obtained by selective operation of the calling device.

It is a still further object of the invention to provide, in an automatic telephone system, an

improved trunk selecting circuit which is so arranged that any one of a plurality of trunk lines may be seized by an automatic switch having access thereto over a single set of outlet contacts included in the switch, thus minimizing the number of contact sets required in the switch to serve a given number of lines.

The features of the invention, as outlined above, are illustrated in their embodiment in a system which comprises a remotely controlled automatic exchange arranged to serve a small number of lines and to function as a tandem exchange between the control or central exchange and a distant manual office. The automatic switching apparatus of the remotely controlled exchange comprises a plurality of finder-connector links having trunk lines individual thereto and extending to an operator's position in the control office, and common equipment including a link distributor for assigning the links to the use of calling ones of the lines terminating at the remotely controlled exchange. In accordance with one feature of the invention, the switching apparatus of the remotely controlled exchange is so arranged that the link distributor operates in response to the initiation of a call on any one of the lines terminating at the community exchange and is held operated until the call is answered at the distant operator's position; means being provided in the individual links, operative in response to the answering of the call at the operator's position, for initiating the operation of the distributor included in the common equipment to select an idle one of the links. The common equipment also includes a timing device which, in combination with certain of the relays embodied in the common equipment, functions to cause the distributor to assign a new link to the use of a calling line in the event the finder portion of the first assigned link fails to find the calling line within a predetermined time interval, and also to cause an assigned link to be released in the event a call as routed to the distant operator's position is not answered within the predetermined time interval. In accordance with another feature of the invention, each link is provided with a circuit including its associated trunk line for transmitting to the operator's position a paystation tone signal current in order to give the operator supervision of calls originating at substations of the paystation type. The arrangement is such that this circuit is completed when a call originating at a paystation is answered at the control operator's position. The paystation identifying signal, as thus transmitted to the control operator's position, is terminated a predetermined time interval thereafter through the provision of means comprising a timing device embodied in the common equipment for interrupting the signal current circuit. The common equipment further comprises apparatus for partially controlling the incoming call signal lamps provided at the operator's position and individually associated with the control trunk lines extending between the links of the community exchange and the operator's position.

Certain of the subscribers' lines terminating at the community exchange are of the multiparty type and the arrangement of the automatic switching apparatus included in the exchange is such that lines of this character are not guarded against incoming calls while occupied with reverting calls, a monitoring operation of the part of the operator being required in order to de-

termine the idle or busy condition of such lines. In order that the operator may inform a calling subscriber that a desired called line is occupied with a reverting call without conversing with the calling party after the busy condition of the called line is ascertained, the link circuits are arranged in an improved manner such that the operator may, by simply releasing the connection, cause the operated link to be held operated for a predetermined time interval during which a busy tone signal is transmitted from the link over the calling line to inform the calling party that the desired line is busy. More particularly, each connector switch is provided with a ringing control relay which is operative to connect the conductors of a selected called line to a source of ringing current under the control of the operator in the distant exchange. Each link further comprises a timing device, together with means responsive to the release of a connection routed by way of the link for initiating the operation of the timing device in the event the connection is released at the operator's position prior to operation of the ringing control relay and for impressing a busy tone signal upon the calling end of the connection. Apparatus controlled by the timing device is also provided for maintaining the link operated for a predetermined time interval following the release of the connection at the operator's position. During this predetermined time interval the busy tone signal continues, thus informing the calling subscriber that the desired line is busy. In accordance with another feature of the invention, the above-mentioned ringing control relay, as embodied in each link, is operative to connect a selected called line to the ringing current source of the community exchange for variable time intervals determined by operation of the calling device provided at the operator's position and by means of which the connector portion of the link is directly controlled.

Each of the connector switches provided in the remotely controlled exchange is provided with a normal position and is operative to any one of a plurality of positions to select one of the lines terminating at the exchange. In accordance with a further feature of the invention each link has associated therewith a circuit, including the associated control trunk, for transmitting a signal to the central exchange operator's position; means being provided in the link, operative in response to the initiation of a call on the associated control trunk for completing the circuit only if the connector portion of the link occupies its normal position. The arrangement is such that when the finder switch of the link operates to seize a calling line, the control apparatus of the link functions to interrupt the signaling circuit just described. In accordance with another feature of the invention an additional signaling arrangement is provided for enabling the central exchange operator to be apprised at all times as to the condition of the apparatus embodied in the remotely controlled exchange. More particularly, means are provided for normally energizing the above-mentioned signaling circuits, individual to the links, with current having one signaling characteristic, and for energizing the circuits with current having a different signaling characteristic when a fault is present in the apparatus located in the remotely controlled exchange.

Interoffice calls between the central and manual exchanges of the system are routed over a

group of trunk lines extending between the community exchange and the central exchange. The connector portion of each of the finder-connector links located in the community exchange has access to this group of trunk lines. More particularly, the connector switches of the community exchange include corresponding sets of outlet contacts, and each of the switches has access to all of the trunk lines over a single predetermined set of outlet contacts which corresponds to the predetermined contact set in each of the other switches. The trunk lines have associated therewith preselecting apparatus which is operative in response to seizure of any one of the lines by one of the connector switches for selecting another one of the lines for seizure by the other switches, providing an idle one of the lines is available, and operative, when all of the lines are busy, for marking the trunk lines as busy in the predetermined contact sets of the nonoperated one or ones of the connector switches.

Further features of the invention relate to the particular arrangement of the circuit elements whereby the above and additional operating features are attained.

The novel features believed to be characteristic of the invention are set forth with particularity in the appended claims. The invention, both as to its organization and method of operation, together with further objects and advantages thereof, will best be understood by reference to the specification taken in connection with the accompanying drawings, in which Figures 1 to 6, inclusive, illustrate a telephone system having incorporated therein the features of the invention as briefly outlined above; Fig. 7 illustrates an adapter circuit adapted for use in combination with one of the line circuits shown in Fig. 1; and Fig. 8 illustrates the manner of arranging Figs. 1 to 6, inclusive, to form a complete system.

Referring to the drawings, the system there illustrated comprises a manual office 20, a central exchange including an operator's position 25, and a small community exchange, which is adapted to serve as a tandem exchange between the central exchange and the manual office 20 and includes the switching apparatus illustrated in detail in Figs. 1, 2, 3, 5 and 6. This apparatus, in the arrangement illustrated, is adapted to serve a total of twenty-two trunk and subscribers' lines terminating at the community exchange, which lines include the two subscribers' lines 10 and 11, respectively, and the trunk lines 12, 13 and 14 extending between the community exchange and the manual office 20. The subscribers' lines may be of the single party type or the multiparty type, as required. Thus, the lines 10 and 11 are illustrated as being of the multiparty type, the line 10 having associated therewith two substations A and B and the line 11 having associated therewith the substations C and D. The indicated substations A, B, C and D are of the local battery, magneto type, a hand generator being provided at each thereof for transmitting alternating current over the associated line.

The automatic switching apparatus provided in the community exchange comprises four finder-connector links, one of which is indicated generally at 30, and common equipment, as illustrated in Fig. 3, which includes a distributor switch 45 for assigning the links to the use of calling ones of the lines terminating at the exchange in a predetermined order. Each of these lines terminates in the exchange in a line circuit,

5 that associated with the subscriber's line 10 being indicated generally at 16 and comprising a line relay R120 and a cut-off relay R125. The line relay R120 is so constructed that it will operate when its upper winding is energized with either direct or alternating current. Two additional line circuits 17 and 18 are schematically illustrated as being associated with the subscriber's line 11 and the link line 500, respectively. In order to facilitate a description of the mode of controlling the transmission of paystation signal currents from the links of the community exchange to the distant control operator's position 25, the line circuit 16 associated with the subscriber's line 10 is illustrated, for purposes of explanation only, as including a paystation signal current transmission circuit.

Each of the finder-connector links provided in the community exchange has associated therewith a trunk line which extends to the operator's position 25 in the distant central exchange. Thus, the link 30 includes a repeating coil 393 which terminates one end of a trunk line 15 extending to the trunk circuit apparatus illustrated in Fig. 4 and provided at the operator's position 25. This trunk circuit apparatus comprises a repeating coil 405, one side of which is normally connected to the conductors of the trunk line 15 and the other side of which is connected to the contact springs of a call and answer jack 400. The trunk circuit apparatus further includes an incoming call signal lamp 401, a call and answer key 402 and a dial key 403, all of which are individual to the trunk line 15, and a calling or impulsing device 404 which may be common to the group of trunk lines extending to the operator's position 25. There is further included in the trunk circuit apparatus individual to the trunk line 15 a plurality of control relays R420, R430, R440, R450, R460 and R470, the first two of which are provided for the purpose of controlling the connection of the impulsing device 404 to the trunk line 15. The remaining four relays are provided in order to control the operation of the signal lamp 401 and the operation of the supervisory signal lamp conventionally embodied in the operator's cord circuit, not shown.

Referring now more particularly to the arrangement of the finder-connector links provided in the remotely controlled community exchange, the link 30 is illustrated as comprising a finder switch 35 and a connector switch 40, both of which are of the well-known rotary type. More specifically, the switch 35 comprises four sets of bank contacts 100 to 103, inclusive, wipers 104 to 107, inclusive, individually associated with the contact sets, and means comprising a motor magnet 108 and a ratchet and pawl mechanism, not shown, for driving the enumerated wipers over the contacts of their respective associated contact sets. For the purpose of arresting the operation of the finder switch 35, when the wipers of this switch have been operated into engagement with a set of contacts terminating a calling line, there is provided in the finder portion of the link a line test relay R130. An alternating current relay R131 is also provided in the finder portion of the link for the purpose of controlling the supervisory signal lamp embodied in the operator's cord circuit to give the operator disconnect supervision in the manner described more fully hereinafter. The connector switch 40, which is similar in construction to the switch 30, comprises five sets of

contacts 280 to 284, inclusive, wipers 285 to 289, inclusive, individually associated with the enumerated contact sets, and means comprising a motor magnet 290 and a ratchet and pawl mechanism, not shown, for driving the enumerated wipers over the contacts of their respective associated contact sets. The finder and connector portions of the link are coupled together for the transmission of signal currents therebetween through the provision of a repeating coil 110. The relay equipment provided in the connector portion of the link comprises a pair of signal lamp control relays R140 and R145, the first of which is of the alternating current type, a line or pulsing relay R150, a slow-acting hold relay R155, and a combined line switching and link release relay R160. This equipment further includes a slow-acting impulse responsive relay R170, a busy test relay R200, a combined line switching and digit transfer relay R210, a control relay R220, and a second digit transfer relay R230. In order to select the side of a called line over which ringing current is to be projected, there are provided two additional relays R270 and R275, each of which is of the two-step type. The connection of a called line to the ringing current source conventionally provided in the community exchange is under the control of a ringing control relay R260 which is arranged to be controlled by a slow-to-release impulse responsive relay R250. In order to hold the link 30 operated, under certain conditions, for a predetermined time interval after a connection routed by way thereof has been released at the operator's position 25, there is provided a timing device in the form of a pendulum-type relay R240 which is arranged to control the operation of a slow-to-release relay R245. The latter relay, in turn, is arranged to prevent the completion of certain release circuits, described more particularly hereinafter, for a predetermined time interval determined by the operation of the pendulum relay R240.

The equipment commonly associated with the finder-connector links provided in the community exchange is illustrated in Fig. 3 as comprising the link distributor switch 45 and a timing device 50. More particularly, the distributor switch 45 is of the well-known rotary type and comprises six sets of contacts 300 to 305, inclusive, of ten points each, wipers 306 to 311, inclusive, individually associated with the enumerated contact sets, and means including an operating magnet 312 for driving the indicated wipers over the contacts of their respective associated contact sets. The timing device 50 includes a cyclically operative rotary switch 390 which comprises a single set of contacts, a wiper 391 associated with this contact set and a motor magnet 392 for driving the wiper 391 over its associated contacts. Operation of this rotary switch is effected through the provision of a group of cyclically operating relays R365, R370 and R375, each of which is of the slow-to-operate type. In order to effect the release of an assigned link a predetermined time interval after operation thereof is initiated, the rotary switch 390 is arranged to control a pair of cycle counting relays R385 and R380, which relays are operative in the order named in response to succeeding cycles of operation of the indicated rotary switch. The common equipment illustrated in Fig. 3 also includes a start relay R320, a pulsing relay R340, and a pair of additional timing devices in the form of two pendulum-type relays R330 and R350. The first of

these relays, namely, the relay R330, in combination with the slow-to-operate relay R335, is provided for the purpose of controlling the operation of the signal lamp control relay R460 included in the trunk circuit apparatus terminating the trunk line 15 at the operator's position 25 and the similar signal lamp control relays individually embodied in the trunk circuits respectively terminating the other trunk lines extending to this operator's position. The second timing device, namely, the pendulum-type relay R350, in combination with the slow-to-operate relay R360, is provided for measuring the interval during which a paystation tone signal is transmitted to the operator's position 25 on a call originating on one of the paystation lines terminating at the community exchange. This pair of relays also functions to control the distributor switch 45 in its operation to hunt for an idle link. The common equipment further comprises an exchange battery 5 for supplying current to the various relays and operating magnets, together with a rectifier 394 for maintaining the battery 5 properly charged. Ringing current and the usual busy and dial tone signal currents are supplied by a converter which comprises a transformer 392, and a vibrator and control relays collectively indicated at 393. There is also provided a slow-acting relay R375' which functions periodically to interrupt the converter output voltage, thereby to provide an interrupted signal current which serves for busy line signaling purposes. More particularly, the arrangement of the converter is such that operation thereof is initiated when ground potential is impressed upon the start conductor, not shown but extending thereto. This occurs when any one of the links is seized and is performed in a manner well understood in the art. When operation of the converter is initiated the conductor C397' is grounded to complete an obvious circuit for energizing the relay R375'. Upon operating, this relay completes, at RA376', a path including the condenser 398 for transmitting signal current over the conductor C249. At RA377', the relay R375' short-circuits its lower winding. The relay R375' is so constructed that it will not remain operated when its upper winding is alone energized. Accordingly, it will be apparent that this relay alternately operates and restores periodically to complete the above-traced signal current path. In order to control the previously mentioned circuits for transmitting to the central exchange operator's position signals indicative of the condition of the apparatus in the remotely controlled exchange, there is provided a signal control relay R380' which is arranged to be controlled by a battery charge test relay R385' and also by the fuse links, not shown, which are individual to the various current responsive devices included in the switching equipment.

As indicated previously, the trunk preselecting apparatus illustrated in Figs. 5 and 6 in association with the interoffice trunk lines 12, 13 and 14, is so arranged that each of the connector switches provided in the community exchange has access to all of the trunk lines by way of a single set of outlet contacts. To this end, four individual and disconnected link lines 504 to 507, inclusive, are provided, which lines are individually terminated at corresponding sets of contacts in the four connector switches of the community exchange. Thus, the conductors of the link line 504 are illustrated as being connected to the respective eighth contacts of the

contact sets 260, 281 and 283 embodied in the connector switch 40. The remaining three link lines 506 to 507, inclusive, are similarly connected to the respective eighth contacts of the three other connector switches. These four link lines are not multiplied together. Since each of the indicated trunk lines is of the two-way type, such that calls may be routed thereover in either direction, provisions are made for rendering these lines accessible to the four finder switches provided in the community exchange. To this end, three link lines 500, 502 and 503, individual to the trunk lines 12, 13 and 14, respectively, are provided which individually extend to line circuits identical in arrangement with the line circuit 16. The line switching operations required incident to the selection and use of the trunk lines 12, 13 and 14 are achieved through the provision of four groups of trunk selecting relays, which groups of relays individually correspond to the four connector switches. The first group of trunk selecting relays, namely, that individual to the link 39, is illustrated as comprising three relays R540, R550 and R560, which individually correspond to the trunk lines 12, 13 and 14, respectively. Similarly, the fourth group of trunk selecting relays, namely, that individual to the fourth link, not shown, comprises the three relays R510, R520 and R530, which also individually correspond to the trunk lines 12, 13 and 14, respectively. In order to simplify the disclosure, the groups of trunk selecting relays individual to the second and third links have not been illustrated in the drawings. The groups of trunk selecting relays have commonly associated therewith a group of control relays R600, R610, R620, R630, R640, R650 and R660, the first three of which individually correspond to the trunk lines 12, 13 and 14, respectively, and the last three of which also individually correspond to the three trunk lines in the order enumerated. The relay R630 is an all-trunks-busy relay and is provided for the purpose of marking the trunk lines as busy in the bank contacts of the nonoperated connector switches when an all busy condition of the trunks 12, 13 and 14 prevails.

Operation of the system

Referring now to the operation of the system and considering first a call initiated at the substation A and intended for the substation C associated with the line 11, to initiate the call the calling party operates the hand generator provided at the substation A, thereby to project alternating ringing current over the line 10 and through the upper winding of the line relay R120. When energized by the alternating ringing current, the relay R120 operates to complete, at RA121, an obvious holding circuit for itself. At RA122, the relay R120 completes an obvious path for impressing ground potential upon the contact of the contact set 102 which corresponds to the line 10, thereby to mark this line as the calling line in the contacts of the switch 35. At RA123, the relay R120 completes a circuit for energizing the distributor start relay R320 in series with the operating magnet 312, this circuit extending by way of the grounded all-links-busy conductor C343, RA123, the distributor start conductor C314, RA338, the winding of R320, the armature 313 and the winding of the magnet 312 to battery. Assuming that the wipers of the distributor switch 45 are standing in engagement with the contacts corresponding to the link 39, with the contacts corresponding to the link 30, a branch circuit is also completed for energizing

the magnet 290 of the connector switch 40. This branch circuit extends by way of the grounded start conductor C314, RA338, the winding of R320, RA325, the wiper 310, C344, RA169, C194, RA219', RA238', the armature 291 and the winding of the magnet 280 to battery. Due to the relatively high resistance of the winding of the relay R320, the magnets 312 and 290 are insufficiently energized to operate when this circuit is completed. The relay R320, however, operates to complete, at RA327, a multiple circuit for energizing its own winding in series with the winding of the magnet 312. At RA328, the relay R320 completes circuits, described hereinafter, for initiating the operation of the timing device 50. At RA326, the relay R320 prepares a circuit, traced hereinafter, for energizing the pendulum-type relay R330 in series with the signal control relay R145. At RA325, the relay R320 opens a point in the above-traced branch circuit extending through the winding of the magnet 290, and prepares a circuit for energizing the pendulum-type relay R350. At RA324, the relay R320 prepares a holding circuit for the link pulsing relay R340. At RA323, the relay R320 prepares a circuit for transmitting pay-station tone signal current to the distant operator's position 25 and, in so doing, prepares a circuit for energizing the relay R340. At RA322, the relay R320 prepares a holding circuit for the test relay R130 embodied in the finder portion of the link 30.

At RA321, the relay R320 completes a circuit for energizing the operating magnet 108 of the finder switch 35, this circuit extending from ground by way of RA321, RA341, RA351, the wiper 307, C317, RA136 and the winding of the magnet 108 to battery. When this circuit is completed, the magnet 108 operates to condition the associated ratchet and pawl mechanism to step the wipers 104 to 107, inclusive, one step and attracts its armature 109 to complete the above-mentioned circuit for energizing the pulsing relay R340. This latter circuit extends from ground by way of the armature 109, C316, the wiper 306, RA323 and the upper winding of R340 to battery. When energized over this circuit, the relay R340 operates to open, at RA341, the above-mentioned circuit for energizing the magnet 108, causing this magnet to retract its armature 109 and to release the associated ratchet and pawl mechanism so that the wipers of the switch 35 are stepped one step. When the armature 109 falls back, the above-traced operating circuit for the pulsing relay R340 is interrupted, causing this relay to restore to recomplete, at RA341, the previously traced circuit for energizing the magnet 108. Accordingly, the magnet 108 is energized and operates to again complete the operating circuit for the pulsing relay R340. The interrelated operation of the magnet 108 and the relay R340 continues until the wipers of the switch 35 have been advanced into engagement with the set of contacts terminating the calling line 10. More particularly, when the wiper 106 is moved into engagement with the contact having ground potential impressed thereon by the line relay R120, a circuit is completed for energizing the upper winding of the relay R130 in series with the lower winding of the pulsing relay R340, this circuit extending from ground by way of RA122, the wiper 106, the upper winding of R130, C319, the wiper 309, RA352, RA324, and the lower winding of R340 to battery. When its lower winding is en-

ergized over this circuit, the relay R340 remains operated independently of its upper winding, thereby to hold the operating circuit for the magnet 108 open at its armature RA341. Thus, the step-by-step operation of the finder switch 35 is arrested. When its upper winding is energized over the circuit just traced, the relay R130 operates to complete, at the X contacts associated with RA133', a holding circuit for itself, this holding circuit extending from ground at RA322 by way of the wiper 308, C318, RA133' and the lower winding of R130 to battery. Following the completion of this circuit, the relay R130 completes, at RA133, an obvious path for short-circuiting its upper winding. At RA131, the relay R130 completes a circuit for transmitting a signal current over the established calling loop circuit to inform the calling party that the connection has been routed to the operator's position 25. This circuit may partially be traced as extending from one terminal of the dial tone current source, not shown, by way of the condenser 397, C248, RA231, C177, RA156, RA131, C178, RA201, the condenser 206, RA212, C180, the winding 113, the condenser 119, the winding 114, C188 and RA217 to the opposite terminal of the dial tone current source. The alternating character of the current traversing this circuit is such that an induced signal voltage is developed in the repeater windings 111 and 112, which voltage is reproduced by the receiver provided at the calling substation A. At RA136, the relay R130 opens a further point in the operating circuit for the magnet 108. At RA135, the relay R130 prepares operating and holding circuits for certain of the relays embodied in the connector portion of the link. At RA132, the relay R130 completes a circuit, extending by way of the wiper 105 and the private conductor 10c, for energizing the cut-off relay R125. The last-mentioned relay, upon operating, interrupts, at RA127, the holding circuit for the line relay R120. At RA126, the relay R125 opens a point in the operating circuit for the relay R120, thus disconnecting the upper winding of the latter relay from across the conductors of the line 10. The relay R120 now restores to prepare, at RA122, a further point in the above-mentioned circuit for transmitting paystation tone signal current to the operator's position 25. At RA123, the relay opens the above-traced path for impressing ground potential upon the start conductor C314, thereby to interrupt the operating circuit for the relay R320.

The relay R130, upon operating, also completes the above-mentioned circuit for energizing the upper winding of the signal control relay R145 in series with the pendulum relay R330, this circuit extending from ground at RA326 by way of the winding of R330, RA336, the wiper 311, C345, RA134 and the upper winding of R145 to battery. When energized over this circuit, the relay R145 operates to prepare, at RA147, a path for short-circuiting its lower winding and to interrupt, at RA147', a point in the normally completed circuit for energizing the signal lamp control relay R460 included in the trunk circuit apparatus associated with the trunk line 15 and provided at the operator's position 25. This circuit, over which the relay R460 is normally energized, extends from ground by way of the repeater winding 397, the conductor 15a, RA432, the repeater winding 406, the winding of R460, the winding of R450, the winding 407, RA434, the conductor 15b, the winding 396, C346, the resistor 143, RA147' and the

lower winding of R150 to battery. The resistance normally included in this circuit is such that the relay R460 is the only one of the relays energized thereover which is normally operated. When, however, the relay R145 operates to interrupt this circuit, the relay R460 is deenergized and restores to complete a circuit for energizing the relay R470, the latter circuit extending from ground by way of RA421, RA435, RA451, RA461 and the winding of R470 to battery. When energized over this circuit, the relay R470 operates to complete, at RA473, an obvious holding circuit for itself and to complete, at RA471, an obvious circuit for energizing the incoming call signal lamp 401. At RA472, the relay R470 opens a point in a supervisory circuit which is adapted to extend through the contacts of the jack 400 to the operator's cord circuit. The energization of the lamp 401 serves to signal the operator on duty at the operator's position 25 that an incoming call is present upon the trunk line 15 which should be answered.

When the above-traced circuit is completed for energizing the upper winding of the relay R145 in series with the pendulum relay R330, the latter relay is also caused to operate. The relay R330 attracts its armature RA332 into engagement with the associated weighted armature 331, thereby to initiate vibration of the latter armature in the usual manner, and momentarily to complete an obvious operating circuit for the slow-to-operate relay R335. During vibration of the armature 331 the periods of engagement between this armature and RA332 are insufficient to cause the operation of the slow-to-operate relay R335. Thus, the relay R330 functions as a timing device to prevent, for a predetermined time interval following its initial energization, the operation of the relay R335. When vibration of the armature 331 is substantially terminated, the operating circuit for the relay R335 is held completed, and the latter relay operates to complete, at RA337, an obvious holding circuit for itself. At RA338, the relay R335 opens a further point in the previously traced operating circuit for the relay R320. At RA336, the relay R335 interrupts the above-traced series circuit including the winding of the relay R330 and the upper winding of the relay R145, causing both of these relays to restore. The restoration of the relay R330 is without effect. The relay R145, upon restoring, recompiles the above-traced circuit for energizing the lower winding of the relay R150 in series with the respective windings of the relays R450 and R460, thereby to cause the reoperation of the last-mentioned relay. Upon reoperating, the relay R460 functions to open, at RA461, a point in the previously traced operating circuit for the relay R470. Following the reoperation of the relay R460 no further operation of the apparatus occurs until the call is answered at the operator's position 25.

In the event the finder portion of the link 30 fails to find the calling line 10, the timing device 50 provided in the distributor functions to initiate the release of the assigned link and to cause a second link to be assigned to the use of the calling line. This timing device also functions to initiate the release of the link in the event the call is forwarded to the operator's position 25 and is not answered within a predetermined time interval. Operation of the timing device 50 is initiated in response to operation of the distributor start relay R320. More particularly, when the start relay R320 operates, a circuit is completed for energizing the slow-to-

operate relay R365, this circuit extending from ground by way of RA328, the winding of R365, and the resistor 366 to battery. When energized over this circuit, the relay R365 operates to open, at RA361, the path normally short-circuiting the winding of the relay R370, permitting the latter relay to be energized in series with the resistor 374. Shortly thereafter, the relay R370 operates to open, at RA371, a point in the path normally short-circuiting the winding of the third slow-to-operate relay R375, permitting the latter relay to be energized in series with the resistor 378. When the relay R375 operates, it functions to short-circuit, at RA376, the winding of the first slow-to-operate relay R365. Thus, the relays R365, R370 and R375 are caused sequentially to operate and then sequentially to restore. During each cycle of operation of these three relays, a circuit is completed for energizing the operating magnet 392 of the rotary switch 390. More specifically, this circuit is completed each time the relay R370 operates and extends from ground at RA328 by way of RA372 and the winding of the magnet 392 to battery. This circuit is also interrupted, at RA372, each time the three slow-to-operate relays are caused to restore. Each time the magnet 392 is energized and deenergized, it functions to step the wiper 391 one step, so that, after a predetermined number of cycles of operation of the three slow-to-operate relays, the wiper 391 is advanced into engagement with its associated tenth contact. Thereafter, and during the interval of the next cycle of operation of the three slow-to-operate relays when the relays R370 and R375 are concurrently operated, a circuit is completed for energizing the relay R385, this circuit extending from ground by way of RA373, RA377, the wiper 391 and its associated tenth contact, and the winding of R385 to battery. When energized over this circuit, the relay R385 operates to complete, at RA381, an obvious holding circuit for itself and to prepare, at RA386, a circuit for energizing the relay R380. Following the operation of the relay R385, the three relays R365, R370 and R375 and the rotary switch 390 continue to operate until the wiper 391 is advanced into engagement with its associated ninth contact. While in engagement with this contact and during the interval when the two relays R370 and R375 are concurrently operated, the circuit is completed for energizing the relay R380, this circuit extending from ground by way of RA373, RA377, the wiper 391 and its associated ninth contact, RA386, and the winding of R380 to battery. The relay R380, upon operating, completes, at RA382, an obvious holding circuit for itself and prepares, at RA384, a circuit for energizing the operating magnet 312 of the distributor switch 45. Following the operation of the relay R380, the three cyclically operating slow-to-operate relays and the rotary switch 390 continue to operate until the wiper 391 is advanced into engagement with its associated eighth contact. While standing in engagement with this contact, the above-mentioned circuit is completed for energizing the magnet 312 during the interval when the relays R370 and R375 are concurrently operated. This circuit extends from ground at RA373 by way of RA377, the wiper 391 and its associated eighth contact, RA381, and the winding of the magnet 312 to battery. When this circuit is completed, the winding of the start relay R320 is obviously short-circuited. The magnet 312, when energized over the circuit just traced, operates to

condition its associated ratchet and pawl mechanism to step the wiper of the distributor switch 45 one step. Shortly thereafter the relay R370 releases to open at RA373, the operating circuit 5 for the magnet 312. When the magnet 312 is thus deenergized, the ratchet and pawl mechanism associated therewith operates to advance the wipers of the switch 45 one step. Thus, the wipers 306 to 311, inclusive, are advanced out of 10 engagement with the contacts terminating the control conductors individual to the link 30 and into engagement with the contacts terminating the control conductors individual to the next succeeding link. When the winding of the start relay R320 is short-circuited in response to the 15 completion of the above-traced operating circuit for the magnet 312, this relay restores to open the previously traced operating and holding circuits for the relays R330, R335, R340, R365, R370, R375, R380 and R385 included in the distributor, causing the operated ones of these relays to restore. In addition, if the call has been forwarded to the operator's position 25 but has not been answered thereat within the time interval required for the timing device 50 to complete its 20 operation, the previously traced holding circuit for the relay R130 is interrupted at RA322. At RA321, the relay R320, upon restoring, opens a point in the previously traced circuit for energizing the operating magnet 108 of the switch 35, thereby to deenergize this magnet if operated. If operated at the time the start relay R320 restores, the relay R130, upon restoring, functions to open, at RA132, the operating circuit for the 25 cut-off relay R125, causing the latter relay to restore to reprepare the operating circuit for the line relay R120. 30

In the event the link selected by the distributor switch 45, upon the first step taken thereby, is 35 busy at the time it is selected, the guard conductor individual thereto and corresponding to the guard conductor C344 individual to the link 30, is connected to ground. Ground potential is also present upon the five contacts of the contact set 304 which do not correspond to links in 40 use, these five contacts being multipled together and permanently grounded. An alternative circuit is, therefore, completed for energizing the distributor switch operating magnet 312, this circuit extending by way of the grounded guard conductor of the selected link, the wiper 310, RA325, the armature 313 and the winding of the magnet 312 to battery. The completion of this 45 path also results in the continued short-circuiting of the start relay R320, providing ground potential is present upon the distributor start conductor C314. In this regard it is pointed out that ground potential is maintained upon the start conductor C314 by the relay R120 if the 50 operation of the distributor is caused by failure of the finder switch 35 to find the calling line 10. Ground potential will also be applied to this conductor if another calling line is waiting for the assignment of a link thereto. In either case, the distributor start relay R320 is prevented from 55 operating until an idle link is selected. When the magnet 312 is energized over the alternative circuit just traced, it operates to condition the associated ratchet and pawl mechanism to step the wipers 306 to 311, inclusive, a second step and to interrupt, at its armature 313, a point in its alternative operating circuit. Accordingly, 60 the wipers of the distributor switch 45 are advanced a second step or into engagement with 65 another set of contacts. If this other contact 70 75

set terminates the control conductors of a busy link or includes a permanently grounded contact in the contact set 304, the magnet 312 is again energized and deenergized, so that the wipers of the distributor switch 45 are advanced a third step. The stepping operation of the distributor switch continues until an idle link is found. When the wipers of the distributor switch 45 are stepped into engagement with the contacts corresponding to an idle link, no further circuit is available for energizing the magnet 312 due to the absence of ground potential upon the guard conductor corresponding to the idle link. Accordingly, the stepping operation of the distributor switch is arrested and the path, including the wiper 310 and RA325, for short-circuiting the winding of the relay R320 is interrupted. Accordingly, the start relay R320 is permitted to re-operate to initiate the operation of the finder switch of the selected link to search for the calling line in the exact manner just explained with reference to the finder switch 35. In this regard, it will be apparent that if the operation of the distributor resulting from operation of the timing device 50 is due to failure of the finder switch 30 to find the calling line 10, the cut-off relay R125 is not caused to operate and hence the line relay R120 is operated when the second link is selected. Accordingly, when the second link is found and the short circuit across the distributor start relay R320 is opened, this start relay is energized and operates to initiate the operation of the finder portion of the second link to search for the line 10. If, on the other hand, the calling line 10 is found by the finder switch 35 and the call is forwarded to the operator's position 25, but the operator fails to answer the call within the time required for the timing device 50 to complete its operation, the finder switch of the second link is not started in operation to search for the calling line 10. This is true for the reason that when the finder switch 35 finds the calling line 10, the cut-off relay R125 operates to cause the restoration of the line relay R120 and this line relay will not reoperate unless ringing current is again projected over the line 10. During the sequence of operations just described, however, and when the relay R130 restores in response to the release of the distributor start relay R320, the above-traced circuit over which signal current is transmitted to the calling substation is interrupted at RA131. Hence, the signal being transmitted to the calling party is terminated. Accordingly, the calling party is informed that the call has failed and may reinitiate the call by again operating the hand generator provided at the calling substation.

Continuing now with the operation of the apparatus to extend the connection to the desired called substation C, it is pointed out that to answer the call the operator attending the position 25 first inserts the plug terminating her cord circuit in the call and answer jack 400 and thereafter momentarily operates the call and answer key 402 to its off-normal position. When the operator inserts the plug terminating her cord circuit in the jack 400, ground potential is impressed upon the sleeve contact of this jack in the usual manner. Accordingly, when the key 402 is operated to its off-normal position to close the contact springs 412, an obvious circuit is completed for energizing the relay R440. This relay, upon operating, completes, at RA443, an obvious holding circuit for itself so that it is held

operated after the key 402 is released and allowed to return to its normal position. At RA441, the relay R440 opens the circuit for energizing the signal lamp 401. At RA444, the relay R440 interrupts the holding circuit for the relay R470, causing the latter relay to restore and open, at RA471, a further point in the circuit for energizing the signal lamp 401. At RA442, the relay R440 completes a path for short-circuiting the high resistance winding of the relay R460, thereby to exclude the winding of the latter relay from the previously traced series circuit including the winding of the relay R450 and the lower winding of the relay R150. As a result, the marginal relays R450 and R150 both operate, the first-mentioned thereof functioning to open, at RA451, a point in the previously traced operating circuit for the relay R470 before the relay R460 restores. The relay R150, upon operating, prepares, at RA152, the above-mentioned path for short-circuiting the lower winding of the relay R145. At RA153, the relay R150 prepares an alternative circuit, traced hereinafter, for energizing the upper winding of the relay R145.

At RA151, the relay R150 completes a circuit for energizing the slow-acting relay R155, this circuit extending from ground by way of the wiper 281, C181, RA151 and the winding of R155 to battery. The relay R155, upon operating, completes, at RA157, an obvious circuit for energizing the relay R160 and prepares, at RA158, holding circuits, traced hereinafter, for the two relays R270 and R275. At RA156, the relay R155 interrupts the previously traced circuit for conducting signal current through the windings 113 and 114 of the repeater 110, thereby to terminate the signal being transmitted to the calling party. At RA156 and its associated working contact, the relay R155 prepares a further point in the previously mentioned circuit for transmitting paystation tone signal current to the operator's position 25.

The relay R160, upon operating, prepares, at RA163, an alternative circuit for energizing the relay R160 and completes, at RA164, an obvious multiple holding circuit for the relay R155. At RA165, the relay R160 prepares a circuit, traced hereinafter, for energizing the operating magnet 299 of the rotary switch 40. At RA166, the relay R160 prepares a circuit for energizing the slow-acting pulse responsive relay R170. At RA167, the relay R160 connects multiple ground to the release conductor C191. At RA168, the relay R160 completes a multiple holding circuit for the relay R130, this circuit extending from ground by way of RA168, RA133' and the lower winding of R130 to battery. At RA168', the relay R160 opens one of the paths for impressing ground potential upon the all-links-busy conductor C343. At RA169, the relay R160 opens a point in the circuit, traced hereinafter, for energizing the magnet 299 during the release of the link, and completes an obvious path for impressing ground potential upon the link guard conductor C344 individual to the link 30. When this guard conductor is grounded a circuit is completed for energizing the pendulum relay R350, this circuit extending by way of the grounded conductor C344, the wiper 310, RA325 and the winding of R350 to battery. At its armatures RA162 and RA167, the relay R160 connects the link line conductors C348 and C347 to the link line conductors C189 and C188, thereby to complete a talking circuit, including the three repeating coils 110, 393, and 405 between the calling substation

A and the operator's telephone set. Concurrently with the completion of this talking circuit, the previously mentioned circuit is completed for transmitting the paystation tone signal current through the receiver embodied in the operator's telephone set. In this regard, it will be recalled from the preceding description that the paystation tone circuit associated with the line 10 is illustrated in its association with this line for purposes of explanation only. In the present case, one loop of this circuit may be traced as extending from one terminal of the paystation tone current source, not shown, by way of C124, the condenser 119, RA122, the wiper 106, RA133, C319, the wiper 309, the condenser 342, RA323, the wiper 306, C316, RA156, RA131, C178, RA201, the condenser 206, RA212, RA232, C179, RA162, C348, the two windings 394 and 395, the condenser 395', C347, RA167, RA174, C189, RA237 and RA217 to the opposite terminal of the paystation tone current source. Due to the alternating character of the current traversing this circuit, induced voltages are developed in the repeater windings 396 and 397 which cause current to traverse the loop including the trunk line conductors 15_a and 15_b and the windings 406 and 407 of the repeating coil 405. This current is transmitted through the repeating coil 405 to the receiver of the operator's telephone set, thereby to signal the operator that the call originates at a substation of the paystation type.

When the relay R350 is energized over the above-traced circuit, it attracts its armature RA355 into engagement with the weighted armature 354, thereby to initiate vibratory movement of the latter armature. After a predetermined time interval, during which the armatures 354 and RA355 are only intermittently engaged, the vibration of the armature 354 ceases and this armature settles into engagement with the armature RA355 to complete an obvious circuit for energizing the slow-to-operate relay R360. Upon operating, the relay R360 completes, at RA361, a circuit for energizing the distributor operating magnet 312 and, in so doing, short-circuits the winding of the distributor start relay R320. The circuit for energizing the magnet 312 extends from ground at RA361 by way of RA353 and the winding of the magnet 312 to battery. When energized over this circuit, the magnet 312 operates to condition the associated ratchet and pawl mechanism to step the wipers of the switch 45 one step and to open, at its armature 313, a point in the previously traced holding circuit for the relay R320. The relay R320 restores when its winding is short-circuited and interrupts the previously traced operating and holding circuits for the relays R335, R340, R350, R365, R370, R375, R380 and R385. Thus, the operation of the timing device 50 is arrested. Upon restoring, the relay R320 also functions to interrupt, at RA323, a point in the above-traced circuit for transmitting paystation tone signal current to the operator's position 25. The relay R350, upon restoring, interrupts, at RA355 and its associated armature 354, the operating circuit for the relay R360 and opens, at RA353, a point in the above-traced circuit for energizing the magnet 312, whereby the ratchet and pawl mechanism associated with this magnet is permitted to operate and advance the wipers of the distributor switch 45 into engagement with the contact set terminating the control conductors individual to the next link. From this point on the distributor switch 45 is caused to operate step by step

in the manner previously explained until an idle link is found, providing an idle link is available. During such movement of the distributor switch wipers, ground potential is maintained upon the upper winding terminal of the start relay R320 so that this relay is prevented from operating until an idle link is found. Assuming that another idle link is available, the step-by-step operation of the switch 45 is arrested when the wipers of this switch are operated into engagement with the contacts terminating the control conductors of the idle link, at which time ground potential is removed from the upper winding terminal of the start relay R320, permitting this relay to reoperate if a call is present on another of the lines terminating at the community exchange.

In the event all of the links are busy, the step-by-step operation of the distributor switch 45 continues until the wipers of this switch are operated into engagement with their respective associated last contacts. In this regard, it will be noted that the all-links-busy conductor C343 is connected to the last contact of the contact set 304, which contact set terminates the guard conductors individual to the various links. So long as any link is idle, ground potential is maintained upon the indicated all-links-busy conductor. Thus, so long as the link 30 is idle, a path extending from ground by way of RA238, C193 and RA168' is held completed for maintaining ground potential upon the conductor C343. This path is interrupted at RA168' in response to operation of the relay R160, when the call routed through the link 30 is answered at the operator's position 25. Similar multiple paths extending through the contacts of the control relays embodied in the other links are provided, so that ground potential is present upon the conductor C343 so long as any link is idle. Hence, during a hunting operation of the distributor switch 45 the last contact of the contact set 304 is grounded, indicating a busy link, so that the stepping operation of the switch is not arrested and movement of the switch wipers may continue until the idle link is located. When, however, all of the links become busy, all of the above-mentioned multiple paths are interrupted and ground potential is removed from the conductor C343. Accordingly, when the wiper 310 is moved into engagement with the contact terminating this conductor, no further circuit is available for energizing the magnet 312 and the stepping operation of the distributor switch 45 is arrested. If a call is initiated on one of the lines terminating at the community exchange at a time when all of the links are busy, the operation of the line relay associated with the calling line causes the winding of the distributor start relay R320 to be short-circuited. Thus, if a call is initiated on the line 10 at a time when all of the links are busy, the line relay R120, upon operating, short-circuits the winding of the relay R320 over a path extending from the lower terminal of this winding by way of RA338, C314, RA123, C343, the wiper 310 and RA325 to the upper terminal of the relay R320. In such case, however, the line relay individual to the calling line is locked in its energized position so that when a link thereafter becomes available, the link is assigned to the use of the calling line and the call is forwarded to the operator's position 25 in the manner set forth above. Thus, from the preceding description, it will be apparent that when a call is initiated on the line 10, to cause the

operation of the line relay **R120**, this relay is locked energized over a circuit including its lower winding and is not deenergized until the cut-off relay **R125** subsequently operates in response to operation of one of the finder switches to seize the line **10**. When the all-busy condition of the links is terminated, through the release of one of the links, the path controlled by the relays of this link for impressing ground potential upon the all-links-busy conductor **C343** is recompleted. Accordingly, the magnet **312** is again energized and the stepping operation of the switch **45** is initiated. This stepping operation continues until the idle link is found, at which time the absence of ground potential from the guard conductor individual to the idle link causes the de-energization of the magnet **312**. When the wiper **310** is moved out of engagement with its associated last contact, the above-traced path for short-circuiting the winding of the distributor start relay **R320** is interrupted. However, ground potential is maintained upon the upper winding terminal of this relay over a path extending by way of the wiper **310** and **RA325** to maintain the relay short-circuited so long as the distributor switch wipers are being stepped over contacts corresponding to busy links and until the idle link is located. When the idle link is found, the stepping operation of the switch **45** is arrested and the relay **R320** is conditioned to operate. Thus, the selected idle link is conditioned for use in extending another call to the operator's position **25**.

After the talking circuit between the substation A and the operator's telephone set has been established in the manner described above, the operator may converse with the calling party and ascertain the substation or party desired by the calling subscriber. If the call is of the reverting type, that is, a call intended for another substation associated with the line **10**, such, for example, as the substation B, the operator may instruct the calling party as to the code ring designating the desired substation, wait for the calling party to ring the desired substation, monitor the connection until the call is answered, and then release the operated link in the manner described in detail hereinafter. Alternatively, if the operator, upon answering the call, ascertains from the ringing operation being performed at the calling substation that another substation associated with the line **10** is being called, she may wait until the ringing operation is ended and release the operated link. If the calling line **10** is arranged for divided code ringing, the call may be intended for a substation associated with this line which has its ringer connected to the side of the line opposite the side of the line to which the ringer provided at the calling substation is connected. In such case the operator instructs the calling party to hang up and then releases the operated link. The operator next initiates a call to the line **10** by seizing one of the available links and dialing the directory number designating the desired substation. The calling subscriber after waiting a reasonable time interval, during which the call may be routed to the desired substation, again removes his receiver from its supporting hook, thereby to complete the desired talking circuit, assuming the call has been answered at the called substation. The operator, after monitoring the connection to see that the call is answered may release the operated link. It will be noted that when the connection is released at the operator's

position, all of the line equipment associated with the line **10** is released. Accordingly, this line is not guarded against seizure when occupied with reverting calls.

5 In the present case, wherein the call initiated at the substation A is intended for the substation C associated with the line **11**, the operator, upon ascertaining the identity of the called substation, operates the dial key **403** and dials the 10 directory number designating the called substation. When the dial key **403** is operated to its off-normal position, the springs **410** are closed to complete a circuit, extending by way of the 15 grounded sleeve contact of the jack **400**, for energizing the slow-to-release relay **R420**. At the springs **411**, a parallel circuit is completed for 20 energizing the relay **R430**. The relay **R420**, upon operating, opens, at **RA421**, a further point in the previously traced circuit for energizing the 25 signal lamp control relay **R470**. The relay **R430**, upon operating, opens, at **RA435**, a further point in the last-mentioned circuit. At its armatures **RA431** to **RA434**, inclusive, the relay **R430** disconnects the conductors of the trunk line **15** 30 from the windings of the repeating coil **405** and connects these conductors to the pulsing springs of the calling or impulsing device **404**. Thus, two points are opened in the previously traced circuit for energizing the relay **R450** in series with the relay **R150**, and an alternative low resistance circuit including the pulsing springs of the calling device **404** is completed for maintaining the last-mentioned relay operated. The relay **R450**, upon restoring, reprepares, at **RA451**, 35 the operating circuit for the relay **R470**. With the relay **R430** operated, a pulse train comprising one or more impulses is transmitted over the trunk line **15** to the line or pulsing relay **R150** included in the operated link **30** each time the 40 dial of the calling device **404** is moved off normal and then released. The number of impulses in each train is, of course, determined by the numerical value of the digit dialed. In this regard, it is pointed out that the lines terminating in 45 the connector switch **40** are divided into three groups, the first eight contact sets being utilized to terminate a group of eight lines, the ninth set of contact points being reserved as the starting position for the selection of lines in the second group, the contact points numbered from **10** to **17**, inclusive, being utilized to terminate the conductors of the lines in the second group, the eighteenth contact set being reserved as the starting position for the selection of lines in the 50 third group, and the contact points numbered from **19** to **24**, inclusive, being utilized to terminate the conductors of the lines forming the third group. The twenty-fifth set of contacts in the rotary switch **40** represents the home or 55 normal position of this switch, a position which is occupied by the wipers of the switch when the link **30** is idle. It will be apparent, therefore, that in order to select a called line of the first group a single digit of the numerical value 60 designating the called line must be dialed at the operator's position. To select a line of the second group a first digit of nine impulses followed by a second digit designating the desired line must be dialed. To select a line of the third group a first digit of nine impulses, a second digit of nine impulses and a third digit of the 65 numerical value designating the line are required to cause the connector switch **40** to operate to the desired line. In the present case, wherein the called line **11** is the fourth line of 70 75

the second group, the line selecting digits which the operator must dial in order to select this line comprise a first digit of nine impulses, followed by a second digit of four impulses.

During each impulse of the first digit dialed at the operator's position, the impulsive springs of the calling device 404 are opened to interrupt the circuit over which the pulsing relay R150 is being held energized. This relay, upon restoring at the beginning of the first impulse of the first digit, completes a circuit for energizing the slow-acting relay R170 in multiple with the operating magnet 290 of the rotary switch 40, one branch of this circuit extending from ground by way of RA164, RA151, RA166 and the winding of R170 to battery, and the other branch extending by way of RA164, RA151, RA165, C184, RA202, RA214, RA233 and the winding of the magnet 290 to battery. At RA151, the relay R150 also opens a point in the operating and holding circuits for the relay R155. The latter relay, due to its slow-to-release characteristic, remains operated during impulsive.

When energized at the beginning of the first impulse of the first digit, the relay R170 operates to complete, at RA172, a circuit for energizing the relay R220, this circuit extending from ground by way of RA172, C185, RA204, RA215 and the upper winding of R220 to battery. At RA173, the relay R170 prepares a circuit, traced hereinafter, for energizing the relay R250. At RA171, the relay R170 opens a point in the circuit, traced hereinafter, for energizing the busy test relay R200. At RA174, the relay R170 opens a point in the previously described talking circuit extending between the calling substation and the operator's position 25. Due to its slow-to-release characteristic, the relay R170 remains operated during each series of impulses transmitted to the link 30.

As indicated above, each time the line relay R150 restores and reoperates in response to an impulse transmitted thereto over the trunk line 15, it functions to complete and then interrupt the above-traced circuit for energizing the magnet 290. Each time this magnet is energized and then deenergized, it operates to advance the wipers 285 to 289, inclusive, one step. Accordingly, at the end of the first digit of impulses, the indicated wipers are left standing in engagement with the contacts corresponding to the numerical value of the digit. When the wipers of the switch 40 are stepped to their respective first off-normal positions a multiple path is completed for impressing ground potential upon the guard conductor C344, this path extending from ground by way of the wiper 287 and the multiplied first to twenty-four contacts of the contact set 282 to the conductor C344. When the wiper 287 is moved off normal a point is also opened in the previously traced operating circuit for the relay R155. In the present case, wherein a first digit of nine impulses is dialed, the wipers of the switch 40 are advanced into engagement with their respective associated ninth contacts, which contacts are open-circuited so that no relay operations, aside from the sequential release of the relays R170 and R210, occur at the end of the digit and during the interdigit pause between the first and second digits. In this regard, it will be understood that the interdigit pause, during which the line relay R150 remains operated, is of sufficient length to permit the release of the two relays R170 and R220 in the order named.

At the beginning of the second digit, the re-

lays R170 and R220 are caused to reoperate in the exact manner described above. During this digit the wipers of the switch 40 are also advanced at the rate of one step for each impulse of the digit. In the present case, wherein a second digit of four impulses is dialed, the wipers 285 to 289, inclusive, are left standing in engagement with their respective associated thirteenth contacts, i. e., the contacts terminating the conductors of the called line 11, at the conclusion of the digit. Shortly following the end of the second digit and when the relays R170 and R220 sequentially restore, a circuit is completed, at RA222, for energizing the digit transfer relay R230, this circuit extending from ground at RA167 by way of C191, the wiper 289 and its associated thirteenth contact, RA218, RA222 and the winding of R230 to battery. When energized over this circuit, the relay R230 operates to open, at RA231 and its associated resting contact, a further point in the above-traced circuit for projecting signal current over the calling line. At RA231 and its associated working contact, the relay R230 prepares a circuit, traced hereinafter, for projecting busy tone current over the calling line. At RA232 and RA231, the relay R230 opens the multiple connections between the link line conductors C180 and C188 and the link line conductors C348 and C347. At RA233, the relay R230 opens a point in the above-traced circuit for energizing the magnet 290 and prepares a circuit for energizing the relays R270 and R275 in accordance with the impulses of the third digit. At RA234, the relay R230 prepares a circuit for energizing the pendulum relay R240. At RA235, the relay R230 completes an obvious path for short-circuiting the lower winding of the relay R220, thereby to render the latter relay slow to release. At RA236, the relay R230 prepares a circuit for energizing the slow-to-release relay R245. At RA237, the relay R230 completes a holding circuit for itself, this holding circuit extending by way of the grounded release conductor C191, the wiper 289 and its associated thirteenth contact, RA263, RA237 and the winding of R230 to battery. At RA238, the relay R230 opens a further point in the previously traced path for impressing ground potential upon the all-links-busy conductor C343. At RA238', the relay R230 opens a further point in the circuit for energizing the magnet 290 during the release of the link.

The digit dialed at the operator's position 25 following the selection of the called line is utilized to control the two relays R270 and R275, which relays, as indicated previously, are provided for the purpose of determining over which side of a selected called line ringing current is to be projected. Thus, if the line 11 is arranged for divided ringing, such that the ringers provided at certain of the substations associated therewith are connected between one side of the line and ground, while the ringers provided at the other substations associated with the line are connected between the other side of the line and ground, it is necessary, in order to signal the called subscriber, to project ringing current of the proper code over the side of the line to which the ringer provided at the desired substation is connected. The two relays R270 and R275 are so arranged that with the relay R275 restored, ringing current is projected over the negative side of a selected called line, whereas if the relay R275 is operated, ringing current is projected over the positive side of a selected

called line. In order to cause the operation of the relay R270 without energizing the relay R275 a third digit of one impulse must be dialed at the operator's position 25. If both of the relays R270 and R275 are to be operated, a third digit of two impulses must be dialed. Hence, if the ringer provided at the desired substation C is connected between the positive line conductor 11_b and ground, the third digit dialed at the operator's position 25 will comprise two impulses. At the beginning of the first impulse, when the relay R150 restores, the previously traced circuit is completed for energizing the relay R170, which latter relay reoperates to cause the reoperation of the relay R220 and to perform the other functions previously described. A branch of this circuit is completed through the upper winding of the relay R270. This branch circuit extends from ground at RA164 by way of RA151, RA165, C184, RA202, RA214, RA233, RA272 and its associated upper contact, and the upper winding of R270 to battery. When energized over this circuit, the relay R270 partially operates to complete, at the "X" contacts associated with RA273, a path for short-circuiting its lower winding, this path extending from ground at RA164 by way of RA151, RA165, C184, RA202, RA214, RA233, RA272, the lower winding of R270, RA273, C187 and RA158 back to ground. At the end of the open-circuit period of the first impulse, when the line relay R150 reoperates, the short-circuiting path just traced is interrupted at RA151, permitting the two windings of the relay R270 to be energized in series. When this occurs, the relay R270 completes its operation to prepare, at RA271, a point in the circuit for energizing the busy test relay R200 and to prepare, at RA274, a circuit for energizing the relay R210. At RA272 and its associated upper contact, the relay R270 opens a point in its own operating circuit. At RA272 and its associated working contact, the relay R270 prepares a point in the operating circuit for the relay R275. At the beginning of the open-circuit period of the second impulse, when the line relay R150 again restores, the upper winding of the relay R275 is energized over the pulsing circuit which may now be traced as extending from ground at RA164 by way of RA151, RA165, C184, RA202, RA214, RA233, RA272 and its associated working contact, RA271 and the upper winding of R275 to battery. When its upper winding is energized over this circuit, the relay R275 partially operates to complete, at the "X" contacts associated with RA278, a path extending by way of the grounded conductor C187 for short-circuiting its lower winding. At the end of the open-circuit period of the second impulse, this short-circuiting path is interrupted, permitting the two windings of the relay R275 to be energized in series. When this occurs, the relay R275 completes its operation to prepare, at RA276 and RA279, a circuit, traced hereinafter, for projecting ringing current over the positive side of the selected line 11.

Shortly following the end of the third digit, the relay R170 restores in the manner previously explained. Upon restoring, this relay interrupts the operating circuit for the relay R220 and completes, at RA171, the above-traced test circuit including the upper winding of the busy test relay R200. In this regard, it is pointed out that if the selected line 11 is busy, ground potential is present upon the private conductor 11_c thereof. Accordingly, the busy test relay is energized over the test circuit, this circuit extending by way

of the grounded conductor 11_c, the thirteenth contact of the set 280, the wiper 285, RA271, RA221, C182, RA171, C183 and the upper winding of R200 to battery. When energized over this circuit, the relay R200 operates to complete a holding circuit for itself, which holding circuit extends from ground at RA167 by way of C191, RA203 and the lower winding of R200 to battery. At RA204, the relay R200 opens a further point in the operating circuit for the relay R220. At RA205, the relay R200 opens a point in the circuit, traced hereinafter, for energizing the relay R210. At RA202, the relay R200 opens a point in the above-traced pulsing circuit extending to the two relays R270 and R275, and prepares a circuit for energizing the relay R240. Shortly following the operation of the relay R200, the relay R220 restores to open at RA221, a point in the operating circuit for R200, and to prepare, at RA223, the operating circuit for the relay R210.

The relay R200, upon operating, also completes, at RA201, the above-mentioned circuit for transmitting busy tone signal current to the calling subscriber and a branch circuit for transmitting the busy tone signal current to the telephone instrument embodied in the operator's cord circuit. The first of these circuits extends from one terminal of the busy tone current source by way of the intermittently operating armature RA376', the condenser 398, C249, RA201, the condenser 206, RA212, C180, the winding 113, the condenser 119, the winding 114, C188 and RA217 to the opposite terminal of the busy tone current source. Due to the alternating character of this current, a corresponding induced voltage is developed in the windings 111 and 112 which causes the usual busy tone signal to be reproduced by the receiver of the telephone instrument provided at the calling substation A. The branch circuit traversed by the busy tone current extends from one terminal of the busy tone current source by way of the intermittently operating armature RA376', the condenser 398, C249, RA201, the condenser 206, RA212, RA213, RA261, C179, RA162, C348, the windings 394 and 395, the condenser 395', C347, RA167, RA174, C189, RA262, RA216 and RA217 to the opposite terminal of the busy tone current source. The induced voltage developed in the windings 396 and 397 of the repeating coil 393 causes the operation of the receiver embodied in the operator's cord circuit, thereby to signal the operator that the called line is busy. In this regard, it is pointed out that the operator, after dialing the line 55 selecting digits and the digit designating the side of the line over which ringing current is to be projected, restores the dial key 403 to normal to cause the restoration of the relay R430, the re-operation of the relay R450 and the release of the relay R420 in the order named. Thus, the impulsive device 404 is disconnected from the trunk line 15 and the conductors of this trunk line are extended to the repeating coil 405. In other words, when the key 403 is restored to normal, 60 the signaling channel between the operator's telephone set and the link 30 is recompleted so that the busy tone current is reproduced by the receiver of this telephone set. Upon receipt of the busy tone signal the operator may clear out the connection in the manner pointed out more fully hereinafter.

In the event the called line 11 is idle at the time it is selected by the connector switch 40, battery potential is present upon the control conductor 11_c thereof. Accordingly, when the relay

R170 restores at the end of the third digit to complete the above-traced test circuit including the upper winding of the relay R200, the busy test relay is not energized and remains in its restored position. The relay R170, upon restoring, also functions, in the manner previously explained, to open the operating circuit for the relay R220. Shortly thereafter, the relay R220 restores to open, at RA221, a point in the above-traced test circuit and to complete, at RA223, the operating circuit for the relay R210. The last-mentioned circuit extends from ground at RA167' by way of C191, RA274, RA223, RA205 and the winding of R210 to battery. Upon operating, the relay R210 completes, at RA211, a path extending by way of the wiper 285 for impressing ground potential upon the private conductor 11c of the called line 11, thereby to mark this line as busy in the bank contacts of the other connector switches having access thereto. When ground potential is impressed upon the conductor 11c, the cut-off relay embodied in the line circuit 17 operates to disconnect the operating winding of the line relay included in this circuit from across the conductors 11a and 11b of the line, thereby to prevent the line relay from responding to ringing current projected over the line and to clear the line of the impedance represented by the operating winding of this relay. At RA212, the relay R210 opens a point in the above-traced circuits by way of which busy tone current is transmitted to the calling substation and to the operator's position 25. At RA213 and RA216, the relay R210 disconnects the link line conductors C180 and C188 from the link line conductors C348 and C347, whereby, if the called line 11 is occupied with a reverting call, the calling subscriber is prevented from listening to the conversation being held over this line. At RA213 and RA216 and their respective associated working contacts, the relay R210 connects the conductors 11a and 11b of the called line 11 to the link line conductors C348 and C347, respectively, whereby the calling operator may, upon restoring the dial key 403 to normal, monitor the called line for the purpose of determining whether or not this line is occupied with a reverting call. At RA214, the relay R210 opens a point in the previously traced pulsing circuit extending to the two relays R270 and R275 and prepares a circuit, traced hereinafter, for energizing the relay R240. At RA215, the relay R210 opens a point in the above-traced operating circuit for the relay R220. At RA215', the relay R210 prepares the circuit for energizing the relay R250. At RA217, the relay R210 disconnects the link line conductor C188 from ground. At RA218, the relay R210 opens a point in the previously traced operating circuit for the digit transfer relay R230. At RA219, the relay R210 prepares an alternative circuit, traced hereinafter, for energizing the signal control relay R145. Finally, at RA219', the relay R210 opens a further point in the circuit for energizing the magnet 290 of the connector switch 40 during the release of the link.

As explained above, after dialing the line selecting digits and the digit designating the side of the line over which ringing current is to be projected, the operator attending the position 25 is expected to restore the dial key 403 to normal and monitor the called line before causing ringing current to be projected over this line, since otherwise the conversation being held over a selected line occupied with a reverting call might

be interfered with. If the operator ascertains that the called line is busy, she may cause busy tone current to be returned to the calling subscriber and the connection to be released, all in the manner described in detail hereinafter. Assuming that the called line is idle, the operator again operates the dial key 403 to cause the reoperation of the two relays R420 and R430 so that the pulsing springs of the calling device 404 are again included in the circuit for energizing the line relay R150. After performing this operation, the operator may dial the digits of the code designating the desired called substation C. In this regard, it is pointed out that ringing current is projected over the selected side of the selected called line in response to operation of the calling device 404 and, further, the length of each period during which ringing current is transmitted over the called line is determined by the numerical value of each ringing digit dialed. For example, a ringing digit of two impulses may be dialed to produce a short ring at the called substation and a ringing digit of eight impulses may be dialed to produce a long ring at the called substation. Assuming that the code designating the desired substation C is one "long" and one "short," the operator first dials a digit of eight impulses. The line relay R150 responds to the impulses of this digit in the manner previously explained. When the relay R150 restores at the beginning of the first impulse of the digit, it re-completes, at RA151, the previously traced circuit for energizing the relay R170. A branch of this circuit may be traced as extending from ground by way of RA164, RA151, RA165, C184, RA202, RA214, RA234 and the winding of R240 to battery. The relay R240, upon operating, completes, at its armature 241 and the respective associated working contact, a circuit extending from ground at RA236 for energizing the slow-to-release relay R245. The resulting operation of the last-mentioned relay is without effect at this time. The relay R170, upon operating at the beginning of the first impulse of the digit, further prepares, at RA173, the previously mentioned circuit for energizing the relay R250. This circuit is completed in response to the reoperation of the relay R150 at the end of the open circuit period of the first impulse and extends from ground at RA164 by way of RA151, RA173, C186, RA215' and the lower winding of R250 to battery. When energized over this circuit, the relay R250 operates to complete, at RA251, an obvious path for short-circuiting its upper winding, thereby to render itself slow to release. At RA252, the relay R250 completes an obvious circuit for energizing the relay R260. The relay R260, upon operating, completes, at RA262, the above-mentioned circuit for projecting ringing current over the positive side of the selected line 11. This circuit extends from the ungrounded terminal of the secondary winding of the transformer 392 by way of C296, RA219, RA262, RA216, the wiper 288 and its associated thirteenth contact, the conductor 11b and through the series connected ringer and condenser provided at the substation C to the grounded terminal of the secondary winding of the transformer 392.

Since the line relay R150 follows the impulses of the first ringing digit dialed at the calling substation, the previously traced circuit for energizing the relay R250 is alternately completed and interrupted. Due to its slow-to-release characteristic, occasioned by the short-circuited condition of its upper winding, this relay re-

mains operated until the train of impulses is ended. Accordingly, the relay R260 is held in its operated position for the duration of the first ringing digit. Since this digit comprises eight impulses, the ringer provided at the called substation and the other ringers connected between the positive side of the line 11 and ground, are energized for a relatively long time interval.

When the relay R260 operates at the beginning of the first ringing digit, it interrupts, at RA263, the previously traced holding circuit for the digit transfer relay R230. At RA264, the relay R260 opens a point in the above-mentioned alternative circuit for energizing the signal control relay R145. The relay R230, upon restoring, opens, at RA231, a point in the previously traced circuits for transmitting busy tone current to the calling substation and to the operator's position 25. At RA233, the relay R230 opens a further point in the previously traced pulsing circuit extending to the two relays R270 and R275 and reprepares a point in the pulsing circuit extending through the winding of the magnet 290. At RA235, the relay R230 opens the path short-circuiting the lower winding of the relay R220. At RA236, the relay R230 opens the previously traced operating circuit for the slow-to-release relay R245, causing the last-mentioned relay to restore. At RA234, the relay R230 interrupts the above-traced operating circuit for the relay R240, whereby this relay is caused to restore. The relay R240 remains in its restored position during further impulsing. At RA237', the relay R230 opens a further point in its own holding circuit. At RA238, the relay R230 reprepares the path for impressing ground potential upon the all-links-busy conductor C343. At RA238', the relay R230 prepares a point in the previously mentioned circuit for energizing the magnet 290 during the release of the link 30. At its armatures RA232 and RA237, the relay R230 connects the link line conductors C180 and C188 to the link line conductors C178 and C189 and, in so doing, completes a circuit for transmitting a portion of the ringing current by way of the calling line for the purpose of producing the usual ring-back tone signal at the calling substation. The path traversed by this current may, in the present case, be traced as extending from the ungrounded terminal of the secondary winding of the transformer 392 by way of C296, RA279, RA262, the condenser 262', RA237, C188, the winding 114, the condenser 119, the winding 113, C180, RA232, the condenser 261', RA261 and RA276 to the grounded terminal of the indicated transformer winding. Due to the alternating character of this current, a corresponding current is transmitted by induction to the loop circuit extending to the calling substation to be reproduced by the receiver provided at this substation.

At the end of the first ringing digit, the relay R150 is held operated for a time interval sufficient to permit the release of the relays R170, R250 and R260 in the order named. The last-mentioned relay, upon restoring, disconnects, at its armatures RA261 and RA262, the conductors of the called line 11 from the ringing current source, thereby to terminate the ringing interval. At these same armatures, the relay R260 disconnects the link line conductors C180 and C188 from the ringing current source, thereby to terminate the ring-back tone signal. At RA263, the relay R260 reprepares the holding circuit for the digit transfer relay R230. Finally, at

RA264, the relay R260 reprepares the above-mentioned alternative operating circuit for the signal control relay R145. During the second and each succeeding ringing digit dialed at the operator's position 25, the relays R170, R250 and R260 respond, in the exact manner just described, to cause ringing current to be projected over the selected side of the selected called line for a period determined by the numerical value of the digit dialed. During the succeeding ringing digits, the relays R230, R240 and R245 are not affected, since the relay R230 occupies its restored position. Obviously, by repeatedly operating the calling device 404, the operator may code-ring the called substation C as many times as desired.

In order to complete the description of the ringing arrangement it is pointed out that if a selected called line is arranged for bridged ringing, such that the ringer provided at the called substation is bridged across the conductors of the line, the return path of the ringing current would, with the two relays R270 and R275 operated, extend by way of the negative line conductor of the called line, the wiper 286, RA213, RA261 and RA276 to the grounded terminal of the secondary winding of the transformer 392. As explained above, in order to energize the ringer provided at a called substation and connected between the negative line conductor of the line and ground, the first digit dialed at the operator's position following the two line selecting digits is such that the relay R275 is not caused to operate. Accordingly, when the ringing digits are dialed, ringing current is transmitted over a path which extends from the ungrounded terminal of the indicated transformer secondary winding by way of C296, RA276, RA261, RA213, the wiper 286, the negative conductor of the selected line and through the series connected ringer and condenser provided at the called substation to the grounded terminal of the ringing current source.

After ringing the called substation one or more times, the operator may restore the dial key 403 to normal to cause the restoration of the relays R420 and R430 and the reoperation of the relay R450 and thus recomplete the signaling channel between her telephone set and the called line. When this channel is completed, the operator may monitor the connection to determine when and if the call is answered. If the call is not answered within a reasonable time interval, the operator may again actuate the dial key 403 to its off-normal position and operate the calling device 404 to rering the called substation. When the call is answered, the desired talking circuit is completed between the calling and called substations. The branch of this circuit extending to the calling substation A is obvious. The branch of the talking circuit which extends to the called substation C may partially be traced as extending by way of the line conductor 11a, the wiper 286, RA213, RA261, RA232, C180, the winding 113, the condenser 119, the winding 114, C188, RA237, RA262, RA216, the wiper 288 and the line conductor 11b. The branch of this talking circuit over which the operator may monitor the connection may partially be traced as extending from the negative link line conductor C180 by way of RA232, C179, RA162, C348, the repeater windings 394 and 395, the condenser 395', C347, RA161, RA174, C189 and RA237 to the positive link line conductor C188. Assuming that the calling and called substations are of the local

battery type, current for energizing the transmitters respectively provided at these substations is supplied by the local batteries included in the respective substation circuits. After the connection between the calling and called substations is completed in the manner just described, the operator attending the operator's position 25 may monitor the connection for the full length of the conversation if she so desires. Alternatively, the operator may actuate the disconnect key conventionally provided in her cord circuit to disconnect her telephone set from the established talking circuit and rely upon the supervisory lamp embodied in her cord circuit to indicate when the connection is ready to be released.

When the conversation is finished, the calling and called parties are expected to operate the magneto generators respectively provided at their substations for a short time interval. The alternating current relay R131, having its winding bridged across the calling end of the connection in series with the condenser 139, is energized by the ringing current projected over the calling line 10 from the calling substation A when the magneto generator at this substation is operated. The alternating current relay R140, having its winding bridged across the called end of the connection in series with the condenser 142, is similarly energized and operates when the magneto generator provided at the called substation is operated. Each of the indicated alternating current relays is operative to complete the previously mentioned alternative circuit for energizing the signal control relay R145, this circuit extending from ground at RA219 by way of RA264, C190, RA153, one or both of the armatures RA141 and RA138 and the upper winding of R145 to battery. When energized over this circuit, the relay R145 operates to complete, at RA147, a path including the operated armature RA152 for short-circuiting its lower winding, thereby to render itself slow to release. At RA146 and RA147, the relay R145 includes the high resistance upper winding of the pulsing relay R150 in the circuit extending by way of the trunk line 15 and serially including the winding of the relay R150. More particularly, the relay R150 is now energized over a circuit which extends from ground by way of the winding 391, the conductor 15a, RA432, the winding 406, RA442, the winding of R450, the winding 407, RA434, the conductor 15b, the winding 396, C346, the resistor 143, RA163, RA146 and the two windings of R150 in series to battery. Due to the relatively high resistance of the upper winding of the relay R150, the marginal relay R450 restores when this circuit is completed. At RA451, the relay R450 completes the previously traced circuit for energizing the signal control relay R470. The relay R470, upon operating, opens, at RA472, a point in the circuit extending by the tip and ring contacts of the jack 400 over which a signal control relay included in the operator's cord circuit is normally energized. When the last-mentioned relay restores, one of the supervisory lamps included in the operator's cord circuit is energized to signal the operator that the connection routed by way of the link 30 is ready to be released.

The two alternating current relays R137 and R140 remain operated only so long as ringing current is projected over the calling and called ends of the established connection, respectively. When these two relays are both restored, the above-traced alternative circuit for energizing the signal control relay R145 is interrupted at

one or both of the armatures RA138 and RA141. The relay R145 restores after an interval to open, at RA147, a point in the path short-circuiting its lower winding. At RA146 and RA147, the relay 5 R145 removes the upper winding of the pulsing relay R150 from the above-traced circuit including the winding of the relay R450. The lowered resistance of this circuit results in an increase in the current flow through the winding of R450 so that the relay R450 reoperates to open, at RA451, the operating circuit for the relay R470. The relay R470 operates, in turn, to open, at RA472, the circuit for energizing the signal lamp control relay embodied in the operator's cord circuit. The signal lamp included in this circuit is thus deenergized.

In order to release the connection, the operator withdraws the call and answer plug terminating her cord circuit from the jack 400. In response to this operation ground potential is removed 20 from the sleeve contact of the jack 400 to open the previously traced holding circuit for the relay R440, causing this relay to restore and open, at RA442, the path short-circuiting the winding of the high resistance relay R460. The relay R460 now reoperates and the relay R150 included in the link 30 restores. Upon restoring, the relay R150 recompletes the operating circuit for the slow-acting relay R170 and opens the holding circuit for the slow-acting hold relay R155. The relay R155, upon restoring, opens, at RA158, a point in the previously traced holding circuits for the two relays R270 and R275, causing the relay R270 to restore, and the relay R275, if operated, 25 also to restore. Thus, the relays R155 and R160 are caused sequentially to restore in the order named and in an obvious manner. The relay R160, upon restoring, opens, at RA164 and RA166, the completed operating circuit for the relay R170, causing the latter relay to restore. The momentary reoperation of the relay R170, which occurs during the release of the link, is without effect. At RA164, the relay R160 opens a further point in the holding circuit for the relay R155. At RA167', the relay R160 opens a multiple point in the common portion of the previously traced holding circuits for the relays R200, R210 and R230. At RA168', the relay R160 recompletes the previously traced path for impressing ground potential upon the all-links-busy conductor C343. At RA168, the relay R160 interrupts the previously traced holding circuit for the relay R130. The relay R130 now restores to open, at RA132, the operating circuit for the cut-off relay R125, causing the last-mentioned relay to restore and reconnect the upper winding of the line relay R120 across the conductors of the line 10. At RA135, the relay R130 interrupts the holding circuit for the relay R210, causing the last-mentioned relay to restore. The relay R210, upon restoring, opens, at RA211, the path over which ground potential is impressed upon the private conductor 11c of the called line, thereby to cause the release of the cut-off relay embodied in the line circuit 17 in the usual manner. At RA219', the relay R210 completes the previously mentioned circuit for energizing the magnet 290 in order to cause the wipers of the switch 40 to be returned to their respective normal positions. This circuit extends from ground by way of the wiper 287, the multiplied first to twenty-fourth contacts of the contact set 282, C344, RA169, C194, RA219', RA238', the armature 291 and the winding of the magnet 290 to battery. Due to the circuit interrupting action of the ar-

mature 291, the magnet 290 operates buzzer fashion to drive the wipers 285 to 289, inclusive, to their respective home positions. More particularly, when the wiper 287 is moved out of engagement with its associated twenty-fourth contact and into engagement with its associated twenty-fifth contact, the above-traced release circuit is interrupted with the result that the operation of the switch 40 is arrested. When the wiper 287 is disengaged from the multiplied contacts of the set 282, ground potential is also removed from the guard conductor C344, whereby the link 30 is marked as idle in the contacts of the link distributor switch 45. Following the release of the connector switch 40, the link 30 is fully restored to normal and is conditioned for further use.

The manner in which the link 30 is released, following the operation of the connector portion thereof to select a busy called line and when the connection is cleared out at the operator's position 25, is substantially similar to the release of the connection as described in the immediately preceding paragraphs. In this regard, it will be recalled from the foregoing description, that when a called line is busy at the time it is selected, the busy test relay R200 is energized and locked in its operated position at the end of the digit transmitted to the link for the purpose of selecting the side of the called line over which ringing current is to be projected. It will also be recalled that the digit transfer relay R230 remains in its operated position and that the line switch relay R210 is not caused to operate. When the apparatus is in this condition, if the connection is released at the operator's position, the relays R150, R155 and R160 are caused to restore in the order named and in the manner pointed out above. During the interval between the release of the relay R150 and the release of the relay R160, the previously mentioned circuit is completed for energizing the pendulum relay R240, this circuit extending from ground at RA164 by way of RA151, RA165, C184, RA202, RA234 and the winding of R240 to battery. The previously traced circuit is also completed for energizing the slow-acting relay R170, but the resulting operation of this relay is without effect at this time. The relay R240, upon operating, completes, at its weighted armature 241 and the contacts associated therewith, a circuit extending from ground at RA236 for energizing the slow-to-release relay R245. The relay R245, upon operating, completes, at RA246, an obvious holding circuit for itself. At RA247, the relay R245 completes a multiple holding circuit for the relay R130, this multiple circuit extending from ground by way of RA247, C192, RA133' and the lower winding of R130 to battery. With the relay R130 operated, the holding circuits for the two relays R200 and R230 are held completed at the armature RA135. Shortly following the operation of the relay R240, the relay R160 restores to perform the functions previously described and, in addition, to open, at RA165, the circuit for energizing the relay R240. Accordingly, the weighted armature 241 of the relay R240 is released and starts vibrating intermittently to complete the above-traced holding circuit for the relay R245. Due to the slow-to-release characteristic of the relay R245, it remains operated until the vibratory movement of the armature 241 is substantially terminated, at which time this armature assumes a position intermediate its two associated contacts to interrupt the holding cir-

cuit for the relay R245. The relay R245 now restores to open, at RA246, a further point in its holding circuit and, at RA247, the multiple holding circuit for the relay R130. The relay R130, upon restoring, opens, at RA132, the holding circuit for the cut-off relay R125 and interrupts, at RA135, the holding circuits for the two relays R200 and R230, causing all three of these relays to restore. The relay R230, upon restoring, completes, at RA238', the previously traced circuit for energizing the magnet 290 by way of the circuit interrupting contacts associated with the armature 291. As a result, the magnet 290 operates buzzer fashion to return the wipers of the switch 40 to normal, at which time the release circuit is interrupted and ground potential is removed from the guard conductor C344 to mark the link 30 as idle in the distributor switch 45. Thus, the link 30 is fully released and is conditioned for further use. It will be noted that during the interval when the link is held operated due to vibratory movement of the relay R240, the circuit for transmitting busy tone current over the calling end of the connection is maintained completed at the operated armature RA201 of the busy relay R200. Accordingly, the busy signal being transmitted to the calling party is not terminated until the link is substantially released. More particularly, the busy tone signal is maintained for a predetermined time interval following the release of the connection at the operator's position 25 due to the timing action of the pendulum relay R240. The purpose of this arrangement will be apparent from the description appearing immediately hereinafter.

As explained above, the procedure which the operator normally follows in routing a connection to a line terminating at the community exchange is that of dialing the line selecting digits 40 designating the desired line and the digit designating the side of the selected line over which ringing current is to be projected, after which the dial key 403 is restored to normal so that the operator may monitor the called line to determine whether or not the line is occupied with a reverting call. This is necessary since the lines are not guarded against seizure by the connector switches when occupied with reverting calls. Thus, in completing the connection described 50 above, if the line 11 is occupied with a reverting call at the time it is selected by the connector switch 40, guarding ground potential is not present upon the private conductor 11 thereof and hence the busy test relay R200 is not caused to operate. Accordingly, the line switching relay R210 is energized and operates shortly following the dialing of the digit required to determine the side of the line over which ringing current is to be projected. Following the dialing of this digit, the operator, upon monitoring the called line, determines that it is in use and hence does not dial the ringing digits designating the desired substation. Accordingly, the relay R230 is held energized over its holding circuit as traced previously. The arrangement is such that it is not necessary for the operator to again converse with the calling party in order to inform this party of the busy condition of the called line, this service being automatically accomplished when the operator releases the connection. During the release of the link and when the pulsing relay R150 restores, an alternative circuit is completed for energizing the pendulum type relay R240, this circuit extending from ground at RA164 by way of RA151, RA165, C184, RA202 and its associated

upper contact, RA214, RA234 and the winding of R240 to battery. The relay R240, upon operating, completes the previously traced operating circuit for the relay R245, which latter relay, in turn, operates to complete its holding circuit and to complete, at RA247, the previously traced multiple holding circuit for the relay R130. When the relay R155 restores in response to the release of the pulsing relay R159, it completes an alternative circuit for causing busy tone current to be transmitted over the calling end of the connection, this alternative circuit extending from one terminal of the busy tone current source by way of the intermittently operating armature RA376', the condenser 398, C249, RA231, C177, RA156, RA131, C178, RA201, the condenser 206, RA212, C180, the winding 113, the condenser 119, the winding 114, C188 and RA217 to the opposite terminal of the busy tone current source. This current, by induction, causes a corresponding current to traverse the calling loop circuit so that the usual busy signal is reproduced by the receiver provided at the calling substation. The relay R160, upon restoring in response to release of the slow-acting relay R155, opens, at RA165, the above-traced alternative operating circuit for the pendulum relay R240. Accordingly, the weighted armature 241 of the relay R240 is released alternately to complete, at the vibratory contacts associated therewith, a holding circuit for the slow-to-release relay R245. A predetermined time interval thereafter, when the vibratory movement of the armature 241 is terminated, the relay R245 restores to open, at RA247, the holding circuit for the relay R130. From this point on the release of the link is exactly the same as set forth above with reference to the call routed to the line 11 at a time when this line is busy, it being pointed out that the above-traced alternative circuit for transmitting busy tone current over the calling end of the connection is interrupted at two points in response to the release of the two relays R130 and R230.

The arrangement of the switching apparatus is such that the operator attending the operator's position 25 may extend calls routed to her position through the automatic switching equipment in the remotely controlled exchange to any line terminating in the central exchange. Thus, if the above-described call originating at the substation A and routed to the operator's position 25 is intended for a substation associated with a line terminating at the central exchange, the operator may set up the desired connection in the manner conventionally followed in manual office practice. When the operator answers the call at the position 25 by inserting the call and answer plug of her cord circuit in the jack 400, the relays R440, R150, R155 and R160 are caused sequentially to operate in the order named and in the manner described previously. Since, in this case, no dial pulses are transmitted from the operator's position 25 over the trunk line 15 to the connector portion of the link, none of the relays illustrated in Fig. 2 are caused to operate. The relay R160, upon operating, performs the functions described previously, that is, it establishes a connection between the calling substation and the operator's telephone set, marks the link 30 as busy in the bank contacts of the distributor switch 45, and initiates the operation of this distributor to select another idle link. The relay R155, in addition to completing the operating circuit for the relay R160, functions to open, at RA156, the circuit over

which dial tone current is transmitted to the calling substation, thereby to terminate the dial tone signal. After the connection is established, the relays R450 and R470 embodied in the trunk circuit apparatus shown in Fig. 4 and controlled by the relay R145 included in the link 30 are utilized in the exact manner explained above for the purpose of giving the operator a disconnect signal when the connection is released at the calling end thereof. During the release of the connection, the link 30 is released when the operator withdraws the call and answer plug of her cord circuit from the jack 400. In response to this operation, the relays R440, R150, R155 and R160 are caused sequentially to restore in the order named and in the manner previously described. The relay R150, upon restoring, completes the previously traced circuit for energizing the relay R170 in parallel with the operating magnet 290 of the connector switch 40. The resulting operation of the relay R170 is without effect. Shortly following the release of the relay R150, the relay R160 restores to open, at RA165, the circuit for energizing the magnet 290 and, at RA166, the circuit for energizing the relay R170. As a result, the relay R170 restores and the magnet 290 is deenergized, permitting the ratchet and pawl mechanism associated with this magnet to advance the wipers of the switch 40 one step from normal. Immediately the wiper 287 is moved into engagement with its associated first contact, the previously traced release circuit is completed for energizing the magnet 290, and the above-traced path is completed for impressing ground potential upon the guard conductor C344. Accordingly, the wipers 285 to 289, inclusive, are driven back to their respective home positions, at which time the release circuit is interrupted at the wiper 287 and its associated twenty-fifth contact. When the wiper 287 is returned to its home position, ground potential is also removed from the guard conductor C344, whereby the link is marked as idle in the bank contacts of the distributor switch 45. The release of the finder portion of the link is initiated when the relay R160 is deenergized. Thus, when the relay R160 restores, it opens, at RA168, the only completed holding circuit for the relay R130, thereby to cause the sequential restoration of the relays R130 and R125.

Calls routed to the operator's position 25 over lines terminating at the central exchange may be forwarded, under the control of the operator attending this position, to any one of the lines terminating at the distant community exchange or through the automatic switching apparatus provided in this exchange and over one of the interoffice trunk lines 12, 13 and 14 to an operator's position in the distant manual office 20. To initiate such a call the operator inserts the call and answer plug of her cord circuit in the jack 400, thereby to cause the sequential operation of the relays R440, R150, R155 and R160 in the exact manner previously described. When the relay R160 operates a circuit is completed for transmitting to the operator's position 25 a signal indicating that the connector switch occupies its normal position. This circuit extends from one terminal of the signal current source by way of the condenser 397', RA381', C297, the twenty-fifth contact of the set 280, the wiper 285, C176, RA161, RA131, C178, RA201, the condenser 206, RA212, RA232, C179, RA162, C348, the windings 394 and 395, the condenser 395', C347, RA167, RA174, C189, RA237, and RA217 to

the opposite terminal of the signal current source. This current is transmitted by way of the repeater 393, the line 15 and the repeater 405 to the receiver of the operator's telephone set, whereby the usual dial tone signal is reproduced. It will be noted that if the wipers of the connector switch are off-normal the above-traced signaling circuit is not completed. In such case the operator is informed by the absence of the dial tone signal that the link 30 is defective. In the event the rectifier 394 fails, so that charging current is no longer delivered through the winding of the relay R385 to the battery provided in the remotely controlled exchange, the armature RA386' controlled by the relay R385' is restored so that an obvious circuit is completed for energizing the relay R380'. The last-mentioned relay is also energized if one of the fuse links individual to the various current responsive devices embodied in the automatic switching apparatus of the remotely controlled exchange is blown so that ground potential is impressed upon the conductor C395. With the relay R380' operated, current for energizing the above-traced signaling circuit is delivered to this circuit by way of the intermittently operating armature RA376', the condenser 398 and the operated armature 381', whereby the usual busy signal is reproduced by the receiver of the operator's telephone set. The operator is informed by this signal that certain of the apparatus provided in the remotely controlled exchange is defective and may take steps to have the fault located and corrected.

After the relays R440, R150, R155 and R160 have operated, the call may be routed to one of the lines terminating at the community exchange, such, for example, as the line 11, in substantially the same manner as described above with reference to the call originating at the substation A. In this regard, it is pointed out that the above-traced signaling circuit is interrupted at the wiper 285 and its associated normal contact when the wipers of the switch are stepped off-normal during the first series of impulses transmitted to the link. Further, the link 30 is marked as busy in the bank contacts of the distributor switch 45 in response to the operation of the relay R160 to complete, at RA169, the previously traced path for impressing ground potential upon the guard conductor C344. Since, in the present case, the distributor and common equipment, as shown in Fig. 3, are fully released, the application of ground potential to the guard conductor C344 results in the energization of the magnet 312 over a circuit extending by way of the wiper 310, RA325, the armature 313 and the winding of the magnet 312 to battery. The resulting operation of the magnet 312 serves to initiate the operation of the distributor to search for another idle link in the manner previously explained.

After the connection is established, supervision of the called end thereof is attained through the operation of the relays R140, R145, R450 and R470, these relays being arranged to respond to ringing current projected over the called line from the called substation in the exact manner described above with reference to the call originating at the substation A. The release of the link is also accomplished in the manner described above, it being obvious that only the connector portion of the link is restored to normal when the connection is cleared out at the operator's position 25.

Calls routed to the operator's position 25 may be extended by way of the connector portion of one of the links located in the distant community exchange and over one of the trunk lines 12, 13 and 14 to an operator's position located in the distant manual office 20. For example, if the above-described call originating at the substation A is intended for a substation associated with a line terminating at the manual office 20, the operator attending the position 25, upon answering the call and ascertaining the substation desired, may cause the connection to be routed to the operator's position at which the trunk lines 12, 13 and 14 terminate by dialing a line selecting digit of eight impulses followed by two additional digits. The connector portion of the link 30 responds to the impulses of the line selecting digit by operating to select the link line 504 extending to the trunk preselecting apparatus shown in Figs. 5 and 6 in the exact manner described above with reference to the call routed to the substation C associated with the line 11. In this case, the circuit for energizing the digit transfer relay R230 is completed at the end of the first digit since the selected line is included in the first group of lines. Specifically, the circuit extends from ground at RA167' by way of C191, the wiper 289, the eighth contact of the set 284, RA218, RA222 and the winding of R230 to battery. Following the line selecting digit a second digit of one impulse is dialed in order to cause the operation of the relay R270 in the manner previously explained. At the end of this digit the relay R270 fully operates to complete, at RA271, the previously traced test circuit including the upper winding of the busy test relay R200. As explained hereinafter, if all of the trunk lines 12, 13 and 14 are busy at the time the call is initiated, ground potential is impressed upon the private conductor 504c of the link line 504 through operation of the trunk preselecting apparatus illustrated in Figs. 5 and 6. Accordingly, the busy test relay is caused to operate in response to the complete operation of the relay R270. Upon operating the busy test relay functions to complete the previously traced circuits for transmitting the usual busy signal to the operator's position 25 and to the calling substation, thus informing the operator and the calling party that the connection cannot be obtained. Assuming that all of the trunk lines 12, 13 and 14 are idle at the time the call is initiated, the busy test relay R200 is not caused to operate and the previously traced circuit is completed for energizing the line switching relay R210 at the end of the second digit. Upon operating, this relay performs the functions previously described, among which is the completion of a path at RA211 for impressing ground potential upon the private conductor 504c of the link line 504. In response to this operation, a circuit is completed for energizing the relay R540, individual to the link 30 and the trunk line 12. This circuit extends by way of the grounded conductor 504c, RA544, RA554, RA564, C569, RA621, C568 and the winding of R540 to battery. When energized over this circuit, the relay R540 operates to complete, at the X contacts associated with RA543, an obvious holding circuit for itself. At RA541 and RA542, the relay R540 disconnects the trunkline conductors 12a and 12b from the link line conductors 500a and 500b and connects these line conductors to the link line conductors 504a and 504b, respectively. At RA544, the relay R540, upon fully operating, opens a point in its operating circuit as traced above. At RA545, the

relay R540 connects ground to the control conductor 500_c of the link line 500, thereby to cause the operation of the cut-off relay embodied in the line circuit 18. At RA545, the relay R540 also completes a circuit for energizing the relay R660, this circuit extending from ground by way of RA545, C572 and the winding of R660 to battery. The relay R660, upon operating, prepares, at RA662, a point in the chain circuit, traced hereinafter, for energizing the all-trunks-busy relay R630. At RA661, the relay R660 completes an obvious circuit for energizing the relay R620. The relay R620, upon operating, opens, at RA621, a further point in the operating circuit for the trunk selecting relay R540. In a similar manner, the relay R620, at RA624, opens a point in the operating circuit for the first trunk selecting relay R510 which is individual to the trunk line 12 and the link line 507 which extends to the fourth link. At RA622 and RA623, the relay R620 similarly opens points in the respective operating circuits for the relays individual to the trunk line 12 and respectively associated with the link lines 505 and 506 extending respectively to the bank contacts of the second and third links provided in the community exchange. Thus, the trunk selecting relays individual to the trunk line 12, that is, the relays R510, R540, etc. are prevented from operating in response to a second trunk call initiated before the call under consideration is terminated. The relay R660, upon operating, also completes, at RA662, a circuit extending by way of RA651 for energizing the relay R610 which is individual to the second trunk line 13. The relay R610, upon operating, prepares, at RA611, a circuit for energizing the trunk select relay R550 individual to the trunk line 13 and the link line 504. At RA614, the relay R610 similarly prepares a circuit for energizing the trunk select relay R520 individual to the trunk line 13 and associated with the link line 507 extending to the bank contacts of the fourth link provided in the community exchange. At its armatures RA612 and RA613, the relay R610 similarly prepares circuits for energizing the respective trunk select relays, not shown, of the sets individual to the second and third link lines 505 and 506 so that if a call is routed by way of one of these lines the trunk line 13 will be taken for use.

The operator, after dialing the digit required to cause operation of the relay R270, in the manner explained above, and momentarily restoring the dial key 403 in order that she may monitor the connection to determine whether or not all of the trunk lines are busy, reoperates the dial key and dials a short ringing digit of two or more impulses. The ringing relays R250 and R260 respond to the impulses of the third digit in the manner described previously with reference to the call routed to the substation C. The relay R260, upon operating, connects the conductors 12_a and 12_b of the trunk line 12 to the terminals of the ringing current source provided in the community exchange, so that ringing current is projected over the trunk line 12 for the purpose of energizing a drop or a signal control device associated with the distant end of the trunk line 12 in the manual office 20. Thus, the operator in the distant manual office 20 is signaled that an incoming call on the trunk line 12 should be answered. From this point on the connection may be extended to a substation associated with a line terminating at the manual office in the manner conventionally followed in manual office practice. After the connection is established, su-

pervision of the calling end thereof is handled by the operator attending the position 25. In this regard, it will be apparent that the relays R137, R145, R440 and R470 will operate, in the exact manner previously described, to control the supervisory lamp included in the cord circuit in use at the operator's position 25 in response to ringing current projected over the calling end of the connection. The operator attending the position 25, upon receiving a disconnect signal, may signal the distant operator in the manual office 20 by operating the dial key 403 to its off-normal position and reoperating the calling device 404 to cause ringing current to again be projected over the trunk line 12 for the purpose of energizing the signal device or the signal control device associated with the trunk line 12 in the distant manual office 20. Supervision of the called end of the connection is under the control of the operator in the manual office 20 who handles calls routed to the operator's position at which the trunk lines 12, 13 and 14 are terminated. Thus, if the operator at this position receives a disconnect signal, she may signal the operator attending the position 25 by projecting ringing current over the conductors of the trunk line 12 to energize the alternating current relay R140, which latter relay, in combination with the relays R145, R440 and R470, operates in the manner previously pointed out to cause the supervisory signal lamp embodied in the operator's cord circuit to be energized. The release of the operated apparatus located in the community exchange is under the control of the operator attending the position 25; the link 30, through which the connection extends, and the trunk circuit apparatus of Fig. 4 being released in the exact manner described previously with reference to the connection established between the substations A and C. During the release of the link 30 and when ground potential is removed from the private conductor 504_c of the link line 504, the relay R540 is deenergized and restores to open, at RA545, the previously traced operating circuit for the relay R660. At RA545, the relay R540 also disconnects the control conductor 500_c from ground, thereby to cause the release of the cut-off relay embodied in the line circuit 18. At RA541 and RA542, the relay R540 disconnects the trunk line conductors 12_a and 12_b from the link line conductors 504_a and 504_b and reconnects the indicated trunk line conductors to the link line conductors 500_a and 500_b in order that the automatic switching equipment of the community exchange shall be accessible to the trunk line 12 on calls originating at the manual office 20. At RA543, the relay R540 opens a further point in its holding circuit. Finally, at RA544, the relay R540 reprepares a point in its operating circuit. The relay R660, upon restoring, opens, at RA661 and RA662, the respective operating circuits for the two relays R620 and R610, causing both of these relays to restore. The relay R620, upon restoring, reprepares, at its armatures RA621 to RA624, inclusive, the respective operating circuits for the four trunk select relays individual to the trunk line 12 and respectively associated with the link lines 504 to 507, inclusive. The relay R610, upon restoring, opens, at its armatures RA611 to RA614, inclusive, points in the respective operating circuits for the trunk select relays R550, R520, etc., individual to the second trunk line 13 and respectively associated with the link lines 504, 505, 506 and 507.

The automatic switching apparatus provided

in the community exchange is also operative to route connections to the operator's position 25 on calls originating at the manual office 20 and routed by way of the trunk lines 12, 13 and 14. Thus, if the operator at the manual office 20 seizes the trunk line 12, for example, she may cause the call to be forwarded to the operator's position 25 by projecting ringing current over the trunk line 12 to energize the line relay embodied in the line circuit 18. The operation of the line relay included in the line circuit 18 results in the operation of the common equipment illustrated in Fig. 3 to initiate the operation of the finder portion of one of the links to search for the calling link line 500. Assuming, for example, that the link 30 is assigned to the use of the call, when the finder switch 25 finds the link line 500, the operation thereof is arrested and ground potential is impressed upon the control conductor 500c, all in the manner described previously with reference to the call originating at the substation A. When the control conductor 500c is grounded, a circuit is completed for energizing the relay R660, this circuit extending by way of the grounded conductor 500c, the conductor C572 and the winding of R660 to battery. The relay R660, upon operating, completes, at RA661 and RA662, the previously described operating circuits for the relays R610 and R620. The relay R620, upon operating, functions, in the manner explained above, to open a point in the operating circuit for each of the trunk selecting relays individual to the trunk line 12 and respectively associated with the link lines 504 to 507, inclusive, whereby the line 12 is guarded against seizure on calls originating at the operator's position 25 and routed through the automatic switching equipment provided in the community exchange. The relay R610, upon operating, functions, in the manner set forth above, to prepare a point in the operating circuits for the trunk selecting relays R550, R520, etc., individual to the second trunk line 13 and respectively associated with the link lines 504 to 507, inclusive. Thus, the trunk line 13 is selected for use on a call originating at the operator's position 25 and routed through the automatic switching apparatus provided in the community exchange. Aside from the operation of the trunk selecting apparatus shown in Figs. 5 and 6, the call, as initiated on the trunk line 12 in the distant manual office 20, is routed to the operator's position 25 in the same manner as the call originating at the substation A and described previously. Obviously, the call may be forwarded through the connector portion of the operated link 30 to any desired line terminating in the community exchange. The call may also be forwarded to a substation associated with a line terminating in the central exchange in the manner conventionally employed in manual office practice. The supervision and release of the connection following its establishment are exactly the same as described above with reference to the call originating at the operator's position 25 and routed over the trunk line 12 to a line terminating at the manual office 20.

Referring now more particularly to the operation of the trunk circuit apparatus shown in Figs. 5 and 6, if a second trunk call is initiated at the operator's position 25 at a time when the first trunk line 12 is busy, the second trunk line 13 will be utilized in forwarding the call, providing this second line is idle. Thus, if the connection is routed through the connector por-

tion of the link 30, the link line 504 is seized by the connector switch 40 and ground potential is impressed upon the control conductor 504c. Since, under the conditions assumed, the two relays R610 and R620, as well as the relay R660, are operated, a circuit is completed for energizing the relay R550 when the control conductor 504c is grounded. This circuit extends by way of the grounded conductor 504c, RA544, RA554, RA564, C569, RA511, C567 and the winding of R550 to battery. Upon operating, the relay R550 completes, at the X contacts associated with RA553, an obvious holding circuit for itself. At RA554, the relay R550, upon fully operating, opens a point in its operating circuit. At RA551 and RA552, the relay R550 disconnects the conductors of the trunk line 13 from the conductors of the link line 502 and connects these trunk line conductors to the conductors 504a and 504b of the link line 504, thereby to establish a metallic circuit to the manual office 20. At RA555, the relay R550 completes an obvious path for impressing ground potential upon the control conductor 502c, thereby to cause the operation of the cut-off relay embodied in the line circuit individual to the link line 502. At RA555, the relay R550 also completes a circuit, extending by way of C571, for energizing the relay R650. The relay R650, upon operating, opens, at RA651, the previously traced operating circuit for the relay R610, causing the latter relay to restore. At RA651 and its associated working contact, the relay R650 completes a circuit for energizing the relay R600 individual to the third trunk line 14. This circuit extends from ground by way of RA662, RA651, RA641 and the winding of R600 to battery. The relay R610, upon restoring, opens the prepared operating circuits for the trunk selecting relays individual to the trunk line 13 and respectively associated with the link lines 504 to 507, inclusive, whereby the trunk line 13 is guarded against seizure by others of the connector switches having access thereto. The relay R600, upon operating, prepares, at its armatures RA601 to RA604, inclusive, points in the respective operating circuits for the trunk selecting relays individual to the third trunk line 14 and respectively associated with the link lines 504, 505, 506 and 507.

In the event another trunk cell originating at the operator's position 25 and intended for the manual office 20 is initiated before the trunk lines 12 and 13 are released, the trunk line 14 will be utilized in forwarding the call to the operator's position in the manual office 20. Thus, if a call is routed from the operator's position 25 through the connector portion of the fourth finder-connector link provided in the community exchange, the connector portion of the operated link will respond to the impulses of the trunk selecting digit by seizing the link line 507. Shortly following the dialing of the second digit, the control apparatus of the operated link functions to impress ground potential upon the control conductor 507c of the link line 507. As a result, the trunk selecting relay R530 individual to the trunk line 14 is energized and operates. The circuit for energizing this relay extends by way of the grounded conductor 507c, RA517, RA527, RA537, C576, RA604, C573 and the winding of R530 to battery. Upon operating, the relay R530 completes, at the X contacts associated with RA538, an obvious holding circuit for itself. At RA531 and RA532, the relay R530 disconnects the conductors of the trunk line 14

from the conductors of the link line 503. At RA534 and RA535, the relay R530 connects the conductors of the trunk line 14 to the link line conductors 507_a and 507_b, thus establishing a metallic circuit between the operated connector switch and the operator's position in the manual office 20. At RA537, the relay R530, upon fully operating, opens a point in its operating circuit as traced above. At RA533, the relay R530 connects the control conductor 503_c of the link line 503 to ground, whereby the cut-off relay embodied in the line circuit individual to the link line 503 is caused to operate. At RA533, the relay R530 also completes a circuit, extending by way of C570, for energizing the relay R640. The relay R640, upon operating, opens, at RA641, the previously traced operating circuit for the relay R600, causing the latter relay to restore. At RA641, the relay R640 also completes a circuit for energizing the all-trunks-busy relay R630, this circuit extending from ground at RA662 by way of RA651, RA641 and the winding of R530 to battery. The relay R600, upon restoring, opens at its armatures RA601 to RA604, inclusive, points in the respective operating circuits for the trunk selecting relays R560, R530, etc., individual to the trunk line 14 and respectively associated with the link lines 504, 505, 506 and 507. The relay R630, upon operating, prepares, at its armatures RA631, RA632, RA633 and RA634, paths for impressing ground potential upon the respective control or private conductors of the link lines 504 to 507, inclusive. Thus, at RA631, a path extending by way of C569, RA564, RA554 and RA544 is prepared for impressing ground potential upon the control conductor 504_c of the link line 504. Since, in the present case, the link 30 is occupied with a call routed by way of the second trunk line 13, the relay R550 is operated so that the path just traced is open at RA554. If, however, the link 30 had not been operated, none of the three relays R540, R550 and R560 individual to this link would be operated. Accordingly, this path would have been completed to mark the trunk lines as busy in the bank contacts of the connector switch 40, in response to operation of the all-trunks-busy relay R630. In such case, if a trunk call were routed by way of the link 30, the busy test relay R200 would be energized in response to selection of the trunk group and would cause the usual busy tone signal to be transmitted to the operator's position 25 and to the calling substation in the manner previously pointed out. In a similar manner, a path is prepared at RA634 for impressing ground potential upon the control conductor 507_c of the link line 507. This path, which extends by way of C576, RA537, RA527 and RA517, is, in the present case, not completed due to the energized condition of the relay R530. Similar paths, starting from ground at RA632 and RA633, respectively, are prepared for impressing ground potential upon the two other private or control conductors 505_c and 506_c, only those of the paths being completed which extend to the control conductors of link lines not occupied with trunk calls.

When the all busy condition of the trunk lines 12, 13 and 14 is ended, the all-trunks-busy relay R630 is caused to restore and the trunk line which is released is rendered accessible to the connector switches of the community exchange so that it may be used in forwarding calls to the operator's position in the manual office 20. Thus, if the connection routed by way of the fourth link and over the trunk line 14 to the operator's position

in the manual office is released, ground potential is removed from the control conductor 507_c during the release of the link in the community exchange through which the call is routed. When this occurs, the relay R530 is deenergized and restores to open, at RA533, the previously traced circuit for energizing the relay R640. The relay R640, upon restoring, interrupts, at RA641, the operating circuit for the all-trunks-busy relay R630 and completes the previously traced circuit for energizing the relay R600 individual to the trunk line 14. The relay R630, upon restoring, opens, at its armatures RA631 to RA634, inclusive, points in the above-traced paths for impressing ground potential upon the respective control conductors of the link lines 504 to 507, inclusive. The relay R600, upon operating, prepares, at its armatures RA601 to RA604, inclusive, points in the respective operating circuits for the trunk select relays R530, R560, etc., individual to the trunk line 14. Thus, the indicated trunk line is rendered available for further use.

The arrangement of the trunk selecting apparatus shown in Figs. 5 and 6 is such that the trunk lines 12, 13 and 14 are taken for use in the order named. For example, the trunk line 12 will, when idle, always be seized by the connector switch over a link through which a trunk call is routed in preference to the remaining trunk lines 13 and 14. Similarly, the trunk line 13 is used in preference to the trunk line 14 in those cases when both lines are idle and the trunk line 12 is busy. Thus, in the case described above, if the connection routed by way of the link 30 and the trunk line 13 is released shortly following the release of the connection routed by way of the fourth link and the trunk line 14, the first-named trunk line is rendered available for further use when ground potential is removed from the control conductor 504_c to cause the deenergization and restoration of the trunk selecting relay R530. This trunk selecting relay, upon restoring, opens, at RA555, the previously traced operating circuit for the relay R650. Upon restoring, the relay R650, at RA651, interrupts the operating circuit for the relay R600 and completes the operating circuit for the relay R610. Upon restoring, the relay R600 opens the prepared operating circuits for the trunk selecting relays R530, R560, etc., individual to the trunk line 14. The relay R610, upon operating, prepares the respective operating circuits for the trunk selecting relays R520, R550, etc., individual to the trunk line 13. Thus, the trunk line 13 is selected for use in extending a connection to the manual office 20 on the next trunk call routed from the operator's position 25 to one of the links provided in the community exchange. In view of the above explanation, it will be apparent that if the trunk line 12 becomes idle before another trunk call is initiated, this line will be used in preference to the lines 13 and 14. Thus, when the line 12 is released, the conductor C572 is disconnected from ground to cause the release of the two relays R610 and R620. With the relay R610 restored, the operating circuits for the trunk selecting relays individual to the trunk line 13 are open, and with the relay R620 restored, the operating circuit for the trunk selecting relays individual to the trunk line 12 are prepared. Hence, the next trunk call will be routed by way of the trunk line 12.

As indicated in the introductory portion of the specification, the major portion of the lines terminating at the community exchange are of the

magneto type, hand generators being provided at each of the substations associated therewith for the purpose of initiating calls and completing reverting call connections. In order to adapt certain of the lines, such, for example, as the single party lines, so that calls may be initiated without providing hand generators at the substations associated therewith, the adapter circuit illustrated in Fig. 7 may be used. This adapter circuit, which is illustrated as being associated with a subscriber's line 700 extending to the substation E, may be used in conjunction with the line circuit 16 by connecting the line terminals 709_a and 709_b to the line terminals 9_a and 9_b of the line circuit 16. Briefly described, the adapter circuit of Fig. 7 comprises a combined line and battery feed relay R710 and a pair of control relays R720 and R730, the first of which is of the slow-to-operate type and the last of which is of the slow-to-release type. With the adapter circuit connected to the line circuit 16, in the manner just described, if a call is initiated at the substation E, a loop circuit extending by way of the line 700 is completed for energizing the line relay R710. This line relay, upon operating, completes, at RA713, an obvious circuit for energizing the slow-to-operate relay R720. At RA712 and RA714, the relay R710 prepares a connection to the line circuit 16. At RA711 and RA715, the relay R710 completes a circuit for energizing the relay R720, this circuit extending from ground at RA711 by way of RA721, the terminals 709_a and 9_a, RA726, the upper winding of R720, the terminals 9_b and 709_b, RA723, RA715 and the resistor 716 to battery. When this circuit is completed, the line relay R720 operates to complete its holding circuit in the manner previously described and to initiate the operation of the common equipment illustrated in Fig. 3. Shortly following the operation of the relay R710, the relay R720 operates to interrupt, at RA721 and RA723, two points in the above-traced operating circuit for the line relay R720. At these same armatures and their respective associated working contacts, the conductors of the line 700 are connected by way of the condensers 701 and 702, respectively, to the line terminals 709_a and 709_b. At RA722, the relay R720 completes a circuit for energizing the slow-to-release relay R730, which relay, upon operating, opens, at RA731 and RA732, the paths over which the conductors of the line 700 are normally connected to the line terminals 709_a and 709_b. From this point on the connection is routed to the operator's position 25 in the exact manner previously described with reference to the call originating at the substation A. When the connection to the operator's position is established, current for energizing the transmitter provided at the substation E is transmitted to this substation through the windings of the line relay R710 and over the conductors of the line 700. During the release of the connection and when the party at the substation E hangs up, the loop circuit extending through the windings of the relay R710 is interrupted and this relay restores to complete, at RA712 and RA714, a circuit for energizing the alternating current supervisory relay embodied in the finder portion of the link in use. For example, if the link 30 is utilized in completing the desired connection, the relay R131 is energized in response to release of the line relay R710 over a circuit which may be traced as extending from the ungrounded terminal of the ringing current source by way of C296, RA714, RA723, the ter-

minals 709_b and 9_b, the wiper 107, the winding of R137, the condenser 139, the wiper 104, the terminals 9_a and 709_a, RA721 and RA712 to the grounded terminal of the ringing current source.

- 5 The line relay R710, upon restoring, also interrupts, at RA713, the operating circuit for the relay R720, thereby to cause the sequential release of the relays R720 and R730 in an obvious manner. The relay R720, upon restoring, opens, at 10 RA721 and RA723, two points in the above-traced circuit for energizing the supervisory relay R137, thereby to cause the release of the latter relay. The relay R730, upon restoring, recompletes, at RA731 and RA732, the paths over which the conductors of the line 700 are normally connected to the line terminals 709_a and 709_b.

On calls incoming to the substation E, ringing current is projected over the line 700 to energize the signal device provided at this substation over

- 20 a circuit which may partially be traced as extending by way of the terminal 709_a, RA731, the condenser 701, the upper conductor of the line 700, the signal device provided at the called substation, the lower conductor of the line 700, the condenser 702 and RA732 to the line terminal 709_b. From the foregoing explanation, it will be apparent that on a call of this character, the cut-off relay R125 embodied in the line circuit 16 is caused to operate before ringing current is 25 transmitted over the line 700. Accordingly, the upper winding of the relay R720 is disconnected from across the line terminals 9_a and 9_b before the call is answered at the called substation. When the call is answered, the relays R710, R720 30 and R730 are caused sequentially to operate in the order named and in the exact manner just described. In the present case, however, the operation of these three relays is without effect. During the release of the connection and when 40 the receiver at the substation E is replaced upon its supporting hook or cradle to open the loop circuit extending by way of the line 700, the relays R710, R720 and R730 sequentially restore. During the interval when the relay R710 is 45 restored and the relay R720 is operated, ringing current is transmitted over the calling end of the connection to energize the altering current supervisory relay, such, for example, as the relay R140 embodied in the link 30, thereby to cause the energization of the supervisory lamp embodied in the cord circuit being used by the operator at the operator's position 25.

While there has been described what is at present considered to be the preferred embodiment of the invention, it will be understood that various modifications may be made therein, and it is intended to cover in the appended claims all such modifications as fall within the true spirit and scope of the invention.

60 What is claimed is:

1. In a telephone system, a plurality of lines, a plurality of links each including a finder switch having access to said lines, common equipment associated with said links and including a link distributor for assigning said links to the use of calling ones of said lines, an operator's position, a trunk line extending to said operator's position, said common equipment including means responsive to the initiation of a call on one of said lines for causing the finder switch of an assigned link to seize the calling line, means responsive to seizure of said line for routing the call over said trunk line to said operator's position, and means responsive to the answering of the call at said operator's position for initiating

the operation of said distributor to select an idle one of said links.

2. In a telephone system, a plurality of lines, a plurality of links each including a finder switch having access to said lines, common equipment associated with said links and including a link distributor for assigning said links to the use of calling ones of said lines, an operator's position, a trunk line extending to said operator's position, said common equipment including means responsive to the initiation of a call on one of said lines for causing the finder switch of an assigned link to search for the calling line, a timing device in said common equipment, means including said device for causing said distributor to assign a second link to the use of said calling line in the event the finder switch of the first assigned link fails to find said calling line within a predetermined time interval, means responsive to seizure of said calling line for routing the call over said trunk line to said operator's position, and means responsive to the answering of the call at said operator's position for initiating the operation of said distributor to select an idle one of said links.

3. In a telephone system, a plurality of lines, a plurality of links each including a finder switch having access to said lines, common equipment associated with said links and including a link distributor for assigning said links to the use of calling ones of said lines, an operator's position, trunk lines individual to said links and extending to said operator's position, said common equipment including means responsive to the initiation of a call on one of said lines for causing the finder switch of an assigned link to search for the calling line, a timing device in said common equipment, means including said device for causing said distributor to assign a second link to the use of said calling line in the event the finder switch of the first assigned link fails to find said calling line within a predetermined time interval, means responsive to seizure of said calling line for routing the call over the trunk line associated with the assigned link to said operator's position, means including said device for releasing the operated link in the event the call is not answered at said operator's position within a predetermined time interval, and means responsive to the answering of the call at said operator's position for arresting the operation of said device and for initiating the operation of said distributor to select an idle one of said links.

4. In a telephone system, a plurality of lines, a plurality of links each including a finder switch having access to said lines, common equipment associated with said links and including a link distributor for assigning said links to the use of calling ones of said lines, an operator's position, trunk lines individual to said links and extending to said operator's position, said common equipment including means responsive to the initiation of a call on one of said lines for causing the finder switch of an assigned link to search for the calling line, a timing device in said common equipment, means including said device for causing said distributor to assign a second link to the use of said calling line in the event the finder switch of the first assigned link fails to find said calling line within a predetermined time interval, means responsive to seizure of said calling line for routing the call over the trunk line associated with the assigned link to said operator's position, means including said device for releasing the operated link and for causing said distributor to

select an idle one of said links in the event the call is not answered at said operator's position within a predetermined time interval, and means responsive to the answering of the call at said operator's position for arresting the operation of said device and for initiating the operation of said distributor to select an idle one of said links.

5. In a telephone system, a plurality of lines, a plurality of links each including a finder switch having access to said lines, common equipment associated with said links and including a link distributor for assigning said links to the use of calling ones of said lines, an operator's position, a trunk line extending to said operator's position, said common equipment including means responsive to the initiation of a call on one of said lines for causing the finder switch of an assigned link to seize the calling line, means responsive to seizure of said line for routing the call over said trunk line to said operator's position, a timing device in said common equipment, means including said device for releasing the operated link in the event said call is not answered at said operator's position within a predetermined time interval, and means responsive to the answering of said call at said operator's position for initiating the operation of said distributor to select an idle one of said links.

6. In a telephone system, a plurality of lines, a plurality of links each including a finder switch having access to said lines, common equipment associated with said links and including a link distributor for assigning said links to the use of calling ones of said lines, an operator's position, trunk lines individual to said links and extending to said operator's position, said common equipment including means responsive to the initiation of a call on one of said lines for causing the finder switch of an assigned link to seize the calling line, means responsive to seizure of said line for routing the call over the trunk line associated with the assigned link to said operator's position, a timing device in said common equipment, means including said device for releasing the operated link and for causing said distributor to select an idle one of said links in the event the call is not answered at said operator's position within a predetermined time interval, and means responsive to the answering of said call at said operator's position for arresting the operation of said device and initiating the operation of said distributor to select an idle one of said links.

7. In a telephone system, an automatic exchange, a plurality of lines extending to said exchange, a plurality of links in said exchange, each of said links including a finder switch having access to said lines, common equipment associated with said links and including a link distributor for assigning said links to the use of calling ones of said lines, means including said links for establishing connections between said lines, a distant exchange including an operator's position, trunk lines individual to said links and extending to said operator's position, each of said links being operative to route a connection from a seized calling one of said lines over its associated trunk line to said operator's position, means whereby said common equipment is held operated each time a call is routed to said operator's position until the call is answered, and means responsive to the answering of a call at said operator's position for initiating the operation of said link distributor to select an idle one of said links.

8. In a telephone system, a plurality of lines, a plurality of links each including a finder switch having access to said lines, common equipment including a timing device and a distributor for assigning said links to the use of calling ones of said lines; said timing device comprising a cyclically operating timing switch, a group of cyclically operating relays for causing the operation of said timing switch and a pair of control relays sequentially operative during succeeding cycles of operation of said timing switch; an operator's position, trunk lines individual to said links and each extending to said operator's position, said common equipment including means responsive to the initiation of a call on one of said lines for causing the finder switch of an assigned link to search for said calling line and for initiating the operation of said cyclically operating relays, means responsive to the operation of the finder switch of the assigned link to seize said calling line for routing the call over the trunk line associated with the assigned link to said operator's position, and circuit means jointly controlled by one of said control relays and said timing switch for initiating the operation of said distributor to select an idle one of said links in the event the call is not answered at said operator's position within a predetermined time interval.

9. In a telephone system, a plurality of lines, a plurality of links each including a finder switch having access to said lines, common equipment including a timing device and a distributor for assigning said links to the use of calling ones of said lines; said timing device comprising a cyclically operating timing switch, a group of cyclically operating relays for causing the operation of said timing switch and a pair of control relays sequentially operative during succeeding cycles of operation of said timing switch; an operator's position, trunk lines individual to said links and each extending to said operator's position, said common equipment including means responsive to the initiation of a call on one of said lines for causing the finder switch of an assigned link to search for said calling line and for initiating the operation of said cyclically operating relays, means responsive to the operation of the finder switch of the assigned link to seize said calling line for routing the call over the trunk line associated with the assigned link to said operator's position, and circuit means jointly controlled by one of said control relays and said timing switch for initiating the operation of said distributor to select an idle one of said links in the event the finder switch of the first assigned link fails to find said calling line or the call as routed to said operator's position is not answered within a predetermined time interval.

10. In a telephone system, a plurality of lines, a plurality of links each including a finder switch having access to said lines, common equipment including a timing device and a distributor for assigning said links to the use of calling ones of said lines; said timing device comprising a cyclically operating timing switch, a group of cyclically operating relays for causing the operation of said timing switch and a pair of control relays sequentially operative during succeeding cycles of operation of said timing switch; an operator's position, trunk lines individual to said links and each extending to said operator's position, said common equipment including means responsive to the initiation of a call on one of said lines for causing the finder switch of an assigned link to

search for said calling line and for initiating the operation of said cyclically operating relays, means responsive to the operation of the finder switch of the assigned link to seize said calling line for routing the call over the trunk line associated with the assigned link to said operator's position, circuit means jointly controlled by one of said control relays and said timing switch for initiating the operation of said distributor to select an idle one of said links in the event the finder switch of the first assigned link fails to find said calling line or the call as routed to said operator's position is not answered within a predetermined time interval, and means responsive to the answering of the call at said operator's position for initiating the operation of said distributor to select an idle one of said links and for arresting the operation of said timing device.

11. In an automatic telephone system, a plurality of lines, at least one of said lines extending to a substation of the paystation type, a plurality of links each including a finder switch having access to said lines, common equipment associated with said links and including a distributor for assigning said links to the use of calling ones of said lines, said distributor including a group of control relays, an operator's position, a circuit for transmitting a signal current to said operator's position to identify said one line, means responsive to operation of one of said switches to seize said one line for preparing said circuit, means controllable from said operator's position for completing said circuit, and means including one of said control relays for interrupting said circuit.

12. In a telephone system, a plurality of lines, at least one of said lines extending to a substation of the paystation type, a plurality of links each including a finder switch having access to said lines, common equipment associated with said links and including a link distributor for assigning said links to the use of calling ones of said lines, an operator's position, trunk lines individual to said links and each extending to said operator's position, said common equipment including means responsive to the initiation of a call on said one line for causing the finder switch of an assigned link to seize said one line, a circuit including the trunk line individual to said assigned link for transmitting to said operator's position a signal current identifying said one line, means responsive to seizure of said one line by the finder switch of said assigned link for preparing said circuit and for routing the call to said operator's position, means responsive to the answering of the call at said operator's position for completing said circuit and for initiating the operation of said distributor to select an idle one of said links, and means included in said common equipment and responsive to the operation of said last named means for interrupting said circuit.

13. In a telephone system, a plurality of lines, at least one of said lines extending to a substation of the paystation type, a plurality of links each including a finder switch having access to said lines, common equipment associated with said links and including a link distributor for assigning said links to the use of calling ones of said lines, an operator's position, trunk lines individual to said links and each extending to said operator's position, said common equipment including means responsive to the initiation of a call on said one line for causing the finder switch of an assigned link to seize said one line, a circuit including the trunk line individual to said as-

signed link for transmitting to said operator's position a signal current identifying said one line, means responsive to seizure of said one line by the finder switch of said assigned link for preparing said circuit and for routing the call to said operator's position, a timing device included in said common equipment, means responsive to the answering of the call at said operator's position for completing said circuit and for initiating the operation of said timing device, and means controlled by said timing device for interrupting said circuit and for initiating the operation of said distributor to select an idle one of said links.

14. In a telephone system, a plurality of lines, at least one of said lines extending to a substation of the paystation type, a plurality of links each including a finder switch having access to said lines, common equipment associated with said links and including a link distributor for assigning said links to the use of calling ones of said lines, an operator's position, trunk lines individual to said links and each extending to said operator's position, said common equipment including means responsive to the initiation of a call on said one line for causing the finder switch of an assigned link to seize said one line, a circuit including the trunk line individual to said assigned link for transmitting to said operator's position a signal current identifying said one line, means responsive to seizure of said one line by the finder switch of said assigned link for preparing said circuit and for routing the call to said operator's position, a relay included in said link and operative to complete said circuit and to complete a connection between said one line and said operator's position, means responsive to the answering of the call at said operator's position for causing the operation of said relay, a timing device included in said common equipment and operative in response to operation of said relay, and means included in said common equipment and controlled by said timing device for interrupting said circuit and for initiating the operation of said distributor to select an idle one of said links.

15. In a telephone system, a plurality of lines, at least one of said lines extending to a substation of the paystation type, a plurality of links each including a finder switch having access to said lines, common equipment associated with said links and including a link distributor for assigning said links to the use of calling ones of said lines, an operator's position, trunk lines individual to said links and each extending to said operator's position, said common equipment including apparatus responsive to the initiation of a call on said one line for causing the finder switch of an assigned link to seize said one line, a circuit including the trunk line individual to said assigned link for transmitting to said operator's position a signal current identifying said one line, means responsive to seizure of said one line by the finder switch of said assigned link for preparing said circuit and for routing the call to said operator's position, a timing device included in said common equipment, means responsive to the answering of the call at said operator's position for completing said circuit and for initiating the operation of said timing device, means controlled by said timing device for interrupting said circuit and for initiating the operation of said distributor to select an idle one of said links, a second timing device included in said common equipment, said first named means being operative to initiate the operation

of said second timing device, and means controlled by said second timing device for causing said distributor to select an idle one of said links in the event the first assigned link fails to seize said one line or the call as routed to said operator's position is not answered within a predetermined time interval.

16. In a telephone system, a plurality of lines, at least one of said lines extending to a substation of the paystation type, a plurality of links each including a finder switch having access to said lines, common equipment associated with said links and including a distributor for assigning said links to the use of calling ones of said lines, said distributor including a start relay operative to initiate operation of an assigned finder switch to search for a calling one of said lines, an operator's position, a circuit for transmitting to said operator's position a signal current identifying said one line, and means comprising contacts controlled by said start relay for controlling said circuit.

17. In a telephone system, a plurality of lines, at least one of said lines extending to a substation of the paystation type, a plurality of links each including a finder switch having access to said lines, common equipment associated with said links and including a distributor for assigning said links to the use of calling ones of said lines, an operator's position, a circuit for transmitting to said operator's position a signal current identifying said one line, a signal device at said operator's position, a relay and circuits controlled thereby for controlling said signal device, and means included in said distributor for controlling said circuit and the operation of said relay.

18. In a telephone system, a plurality of lines, at least one of said lines extending to a substation of the paystation type, a plurality of links each including a finder switch having access to said lines, common equipment associated with said links and including a link distributor for assigning said links to the use of calling ones of said lines, an operator's position, trunk lines individual to said links and each extending to said operator's position, a signal device at said operator's position, said common equipment including means responsive to the initiation of a call on said one line for causing the finder switch of an assigned link to seize said one line, a circuit including the trunk line individual to said assigned link for transmitting to said operator's position a signal current identifying said one line, a relay normally energized over a circuit including the trunk line individual to said assigned link, means responsive to seizure of said one line by the finder switch of said assigned link for preparing said first named circuit and for interrupting said second named circuit, thereby to cause the release of said relay, means responsive to the release of said relay for causing the operation of said signal device, means responsive to the answering of the call at said operator's position for completing said first named circuit, and means included in said common equipment and operative after said call is answered at said operator's position for interrupting said first named circuit and for recombining said second named circuit.

19. In a telephone system, a plurality of lines, a plurality of finder switches having access to said lines, common equipment associated with said switches and including a link distributor for assigning said switches to the use of calling ones

of said lines, an operator's position, a trunk line individual to one of said switches and extending to said operator's position, a signal device at said operator's position, a first relay normally energized over a first circuit including said trunk line, means responsive to the release of said first relay for causing the operation of said signal device, a second relay individual to said switch and operative to interrupt said first circuit, a third relay included in said common equipment, a second circuit for energizing said second and third relays in series, means responsive to operation of said one switch to seize a calling one of said lines for completing said second circuit, thereby to cause the operation of said second and first relays followed by the operation of said third relay, and means controlled by said third relay for interrupting said second circuit, thereby to cause the release of said second and third relays and the reoperation of said first relay.

20. In a telephone system, a plurality of lines, means including a finder switch and a connector switch for routing a connection from a calling one of said lines to a called one of said lines, said connector switch including means for determining the idle or busy condition of said called line and for transmitting a busy signal over the calling line if the called line is busy, and means operative to hold said switches operated, thereby to continue the transmission of said busy signal over said calling line, for a predetermined time interval after said connector switch is conditioned for release.

21. In a telephone system, a plurality of lines, means including a finder switch and a connector switch for routing a connection from a calling one of said lines to a called one of said lines, said connector switch including a timing device and means for determining the idle or busy condition of said called line and for transmitting a busy signal over the calling line if the called line is busy, means for conditioning said switches for release, said timing device being operative in response to operation of said last-named means, and means controlled by said timing device for holding said switches operated, thereby to continue the transmission of said busy signal over said calling line, for a predetermined time interval after the operation of said last-named means.

22. In a telephone system, a plurality of lines, means including a finder switch and a connector switch for routing a connection from a calling one of said lines to a called one of said lines, said connector switch including means for controlling the transmission of ringing current over a selected called line, means for conditioning said switches for release, and means operative in response to operation of said last-named means for transmitting a busy signal over said calling line in the event said ringing control means is not operated before said switches are conditioned for release.

23. In a telephone system, a plurality of lines, means including a finder switch and a connector switch for routing a connection from a calling one of said lines to a called one of said lines, said connector switch including means for controlling the transmission of ringing current over a selected called line, means for conditioning said switches for release, and means operative in response to operation of said last-named means for transmitting, for a predetermined time interval after said switches are conditioned for release, a busy signal over the calling line only in the

event said ringing control means is not operated before said switches are conditioned for release.

24. In a telephone system, a plurality of lines, means including a finder switch and a connector switch for routing a connection from a calling one of said lines to a called one of said lines, said connector switch including a timing device and means for controlling the transmission of ringing current over a selected called line, means for conditioning said switches for release and for transmitting a busy signal over said calling line, said timing device being operative in response to operation of said last-named means provided said ringing control means is not operated before said switches are conditioned for release, and means controlled by said timing device for holding said switches operated for a predetermined time interval after said switches are conditioned for release, thereby to continue the transmission of said busy signal over said calling line for said predetermined time interval.

25. In a telephone system, a plurality of lines, certain of said lines being of the multiparty type adapted to have reverting call connections established thereover, an operator's position, and means including automatic switching apparatus controllable from said operator's position for routing a connection from a calling one of said lines to a called one of said lines, said automatic switching apparatus including control relays so connected and arranged that a busy signal is transmitted thereby over said calling line in response to the release of the connection at said operator's position in the event said called line is occupied with a reverting call at the time said connection is routed thereto.

26. In a telephone system, a plurality of lines, certain of said lines being of the multiparty type adapted to have reverting call connections established thereover, an operator's position, and means including automatic switching apparatus controllable from said operator's position for routing a connection from a calling one of said lines to a called one of said lines, said automatic switching apparatus including a timing device and control relays so connected and arranged that a busy signal is transmitted thereby over said calling line for a predetermined time interval following the release of said connection at said operator's position in the event said called line is occupied with a reverting call at the time said connection is routed thereto.

27. In a telephone system, a plurality of lines, an operator's position, and means comprising automatic switching apparatus controllable from said operator's position for routing a connection from a calling one of said lines to a called one of said lines, said automatic switching apparatus including means for controlling the transmission of ringing current over said called line and control relays so connected and arranged that a busy signal is transmitted thereby over said calling line in the event said connection is released before said ringing control means is caused to operate.

28. In a telephone system, a plurality of lines, an operator's position, and means comprising automatic switching apparatus controllable from said operator's position for routing a connection from a calling one of said lines to a called one of said lines, said automatic switching apparatus including means for controlling the transmission of ringing current over said called line and a timing device, means responsive to the release of said connection at said operator's position for

initiating the operation of said timing device and for transmitting a busy signal over said calling line in the event said connection is released prior to operation of said ringing control means, and means controlled by said timing device continuing the transmission of said busy signal over said calling line for a predetermined time interval following the release of said connection at said operator's position.

29. In a telephone system, a plurality of lines, a finder-connector link for setting up connections between said lines, an operator's position, a trunk line extending from said link to said operator's position, means including the finder portion of said link for extending a connection from a calling one of said lines by way of said trunk line to said operator's position, the connector portion of said link being controllable over said trunk line from said operator's position to extend said connection to a called one of said lines, and means responsive to the release of said connection at said operator's position for holding said link operated for a predetermined time interval and for transmitting a busy signal over said calling line during said predetermined time interval.

30. In a telephone system, a plurality of lines, a finder-connector link for setting up connections between said lines, an operator's position, a trunk line extending from said link to said operator's position, means including the finder portion of said link for extending a connection from a calling one of said lines by way of said trunk line to said operator's position, the connector portion of said link being controllable over said trunk line from said operator's position to extend said connection to a called one of said lines, a timing device included in said link, means responsive to the release of said connection at said operator's position for initiating the operation of said timing device and for transmitting a busy signal over said calling line, and means controlled by said timing device for holding said link operated for a predetermined time interval after said connection is released at said operator's position, thereby to continue the transmission of said busy signal over said calling line for said predetermined time interval.

31. In a telephone system, a plurality of lines, a finder-connector link for setting up connections between said lines, an operator's position, a trunk line extending from said link to said operator's position, switching apparatus including the finder portion of said link for extending a connection from a calling one of said lines by way of said trunk line to said operator's position, the connector portion of said link being controllable over said trunk line from said operator's position to extend said connection to a called one of said lines, a timing device included in said link, means responsive to the release of said connection at said operator's position for initiating the operation of said timing device and for transmitting a busy signal over said calling line, means controlled by said timing device for holding said link operated for a predetermined time interval after said connection is released at said operator's position, thereby to continue the transmission of said busy signal over said calling line during said predetermined time interval, and means included in said link and controllable over said trunk line from said operator's position for preventing said first-named means from initiating the operation of said timing device.

32. In a telephone system, a plurality of lines,

a finder-connector link for setting up connections between said lines, an operator's position, a trunk line extending from said link to said operator's position, apparatus including the finder portion of said link for extending a connection from a calling one of said lines by way of said trunk line to said operator's position, the connector portion of said link being controllable over said trunk line from said operator's position to extend said connection to a called one of said lines, a timing device included in said link, means responsive to the release of said connection at said operator's position for initiating the operation of said timing device and for transmitting a busy signal over said calling line, means controlled by said timing device for holding said link operated for a predetermined time interval after said connection is released at said operator's position, thereby to continue the transmission of said busy signal over said calling line during said predetermined time interval, a source of ringing current, a ringing relay included in said link and controllable over said trunk line from said operator's position to connect said called line to said source, and means responsive to the operation of said relay for preventing said first-named means from initiating the operation of said timing device.

33. In a telephone system, a plurality of lines, a plurality of finder-connector links for setting up connections between said lines, common equipment including a distributor for assigning said links to the use of said lines, an operator's position, means including the finder portion of an assigned link for extending a connection from a calling one of said lines to said operator's position, the connector portion of said assigned link being controllable from said operator's position to extend said connection to a called one of said lines and including means for marking said link as busy in said distributor, and means responsive to the release of said connection at said operator's position for holding said link operated for a predetermined time interval, thereby to maintain said link busy marking in said distributor during said predetermined time interval, and for transmitting a busy signal over said calling line during said predetermined time interval.

34. In a telephone system, a plurality of lines, a plurality of finder-connector links for setting up connections between said lines, common equipment including a distributor for assigning said links to the use of said lines, an operator's position, means including the finder portion of an assigned link for extending a connection from a calling one of said lines to said operator's position, the connector portion of said assigned link being controllable from said operator's position to extend said connection to a called one of said lines and including means for marking said link as busy in said distributor, means responsive to the release of said connection at said operator's position for holding said link operated for a predetermined time interval, thereby to maintain said link busy marking in said distributor during said predetermined time interval, and for transmitting a busy signal over said calling line during said predetermined time interval, and means including in said link and controllable from said operator's position for preventing said last-named means from holding said link operated.

35. In a telephone system, a plurality of lines, a plurality of finder-connector links for setting up connections between said lines, common equip-

ment including a distributor for assigning said links to the use of said lines, an operator's position, means including the finder portion of an assigned link for extending a connection from a calling one of said lines to said operator's position, the connector portion of said assigned link being controllable from said operator's position to extend said connection to a called one of said lines and including means for marking said link as busy in said distributor, means responsive to the release of said connection at said operator's position for holding said link operated for a predetermined time interval, thereby to maintain said link busy marking in said distributor during said predetermined time interval, and for transmitting a busy signal over said calling line during said predetermined time interval, a source of ringing current, a ringing relay included in said link and controllable from said operator's position to connect said called line to said source, and means responsive to the operation of said relay for preventing said last-named means from holding said link operated.

36. In a telephone system, a plurality of lines, a finder-connector link for setting up connections between said lines, an operator's position, a trunk line extending from said link to said operator's position, means including the finder portion of said link for extending a connection from a calling one of said lines by way of said trunk line to said operator's position, an impulsive device at said operator's position, the connector portion of said link being responsive to operation of said impulsive device to select a called one of said lines, a source of ringing current, a ringing control relay operative to connect said called line to said source in response to operation of said impulsive device following the selection of said called line, means responsive to the release of said connection at said operator's position for holding said link operated for a predetermined time interval and for transmitting a busy signal over said calling line, and means responsive to operation of said relay for preventing said last-named means from holding said link operated.

37. A connector switch having a trunk line extending thereto and comprising, in combination, a line selecting switch, line and release relays for controlling the operation of said line selecting switch, and means responsive to the release of said line relay for impressing a signal voltage upon said trunk line and for holding said connector switch operated independently of said release relay for a predetermined time interval.

38. A connector switch having a trunk line extending thereto and comprising, in combination, a line selecting switch, line and release relays for controlling the operation of said line selecting switch, a source of ringing current, a ringing control relay operative to connect a selected line outgoing from said switch to said source, means responsive to the release of said line relay for impressing a signal voltage upon said trunk line and for holding said connector switch operated independently of said release relay, and means responsive to operation of said ringing control relay for preventing said first-named means from holding said switch operated after the release of said release relay.

39. A connector switch having a trunk line extending thereto and comprising, in combination, a line selecting switch, line and release relays for controlling the operation of said line selecting switch, a source of ringing current, a ringing control relay operative to connect a selected line

outgoing from said switch to said source, a timing device, means responsive to the release of said line relay for impressing a signal voltage upon said trunk line and for initiating the operation of said timing device, means controlled by said timing device for holding said connector switch operated independently of said release relay for a predetermined time interval, and means responsive to operation of said ringing control relay for preventing said first-named means from holding said switch operated after the release of said release relay.

40. In a telephone system, a plurality of lines, an operator's position, a calling device at said operator's position, means including a finder switch for extending a connection from a calling one of said lines to said operator's position, an automatic switch operative to extend said connection to a called one of said lines in response to operation of said calling device, a source of ringing current, and a ringing control relay included in said automatic switch and operative to connect said called line to said source in response to operation of said calling device.

41. In a telephone system, a plurality of lines, an operator's position, a calling device at said operator's position, means including a finder switch for extending a connection from a calling one of said lines to said operator's position, an automatic switch operative to extend said connection to a called one of said lines in response to operation of said calling device, a source of ringing current, and a ringing control relay included in said automatic switch and operative in response to operation of said calling device to connect said called line to said source for variable time intervals determined by the operation of said calling device.

42. In a telephone system, a plurality of lines, a finder-connector link for setting up connections between said lines, an operator's position, a trunk line extending from said link to said operator's position, an impulsive device at said operator's position and operative to transmit trains of impulses over said trunk line to said link, means including the finder portion of said link for extending a connection from a calling one of said lines by way of said trunk line to said operator's position, the connector portion of said link being responsive to one or more trains of impulses transmitted over said trunk line to select a called one of said lines, a source of ringing current, and a ringing control relay operative in response to a train of impulses transmitted over said trunk line to connect said called line to said source for a time interval determined by the number of impulses of said last-mentioned impulse train.

43. In a telephone system, a plurality of lines, a finder-connector link for setting up connections between said lines, an operator's position, a trunk line extending from said link to said operator's position, an impulsive device at said operator's position and operative to transmit trains of impulses over said trunk line to said link, means including the finder portion of said link for extending a connection from a calling one of said lines by way of said trunk line to said operator's position, the connector portion of said link being responsive to one or more trains of impulses transmitted over said trunk line to select a called one of said lines, a source of ringing current, a ringing control relay operative to connect said called line to said source, and means comprising a pulse responsive relay and a slow-to-release relay controlled by said pulse responsive relay for

causing the operation of said ringing relay during each of certain trains of impulses transmitted to said link after said line is selected.

44. In a telephone system, a plurality of lines, certain of said lines being multiparty subscribers' lines arranged for divided ringing, a finder-connector link for setting up connections between said lines, an operator's position, a trunk line extending from said link to said operator's position, an impulsing device at said operator's position and operative to transmit trains of impulses over said trunk lines to said link, means including the finder portions of said link for extending a connection from a calling one of said lines by way of said trunk line to said operator's position, the connector portion of said link being operative to select a called one of said lines in response to one or more trains of impulses transmitted over said trunk line to said link, a source of ringing current, means responsive to a train of impulses transmitted to said link after said called line is selected for selecting the side of said called line over which ringing current is to be projected, and a ringing control relay operative to connect said selected side of said called line to said source in response to each train of impulses transmitted to said link following said last-mentioned impulse train.

45. In a telephone system, a plurality of lines, means including an impulse responsive connector switch for routing a connection from a calling one of said lines to a called one of said lines, a source of ringing current, and a ringing control relay included in said connector switch and operative to connect said called line to said source in response to and for the duration of a train of impulses transmitted to said switch after said line is selected.

46. In an automatic telephone system, a plurality of trunk lines, a plurality of automatic switches having corresponding sets of contacts, each of said switches having access to all of said lines over a single predetermined set of contacts which corresponds to the predetermined contact set in each of the other switches, and trunk preselecting apparatus operative in response to seizure of one of said lines by one of said switches for selecting another idle one of said trunk lines for seizure by the other switches.

47. In an automatic telephone system, a plurality of trunk lines, a plurality of automatic switches having corresponding sets of contacts, each of said switches having access to all of said lines over a single predetermined set of contacts which corresponds to the predetermined contact set in each of the other switches, trunk preselecting apparatus operative in response to seizure of one of said lines by one of said switches for selecting another idle one of said trunk lines for seizure by the other switches, and means operative when all of said trunk lines are busy for marking said lines as busy in the predetermined contact sets of the nonoperated one or ones of said switches.

48. In an automatic telephone system, a plurality of trunk lines, a plurality of automatic switches having corresponding sets of contacts adapted to be connected to lines outgoing from said switches, each of said switches having access to all of said trunk lines over a single predetermined set of contacts which corresponds to the predetermined contact set in each of the other switches, a plurality of sets of relays individual to certain of said switches and each including relays individually corresponding to said trunk

lines, each of said relays being operative to complete a connection between the corresponding trunk line and the predetermined contact set of the corresponding switch, and means responsive to the operation of one of the relays of one of said sets for conditioning the relays of the other sets which correspond to an idle one of said trunk lines to operate in response to operation of the respective corresponding switches to select said plurality of trunk lines.

49. In an automatic telephone system, a plurality of trunk lines, a plurality of automatic switches having corresponding sets of contacts adapted to be connected to lines outgoing from said switches, each of said switches having access to all of said trunk lines over a single predetermined set of contacts which corresponds to the predetermined contact set in each of the other switches, a plurality of sets of relays individual to certain of said switches and each including relays individually corresponding to said trunk lines, each of said relays being operative to complete a connection between the corresponding trunk line and the predetermined contact set of the corresponding switch, means responsive to the operation of one of the relays of one of said sets for conditioning the relays of the other sets which correspond to an idle one of said trunk lines to operate in response to operation of the respective corresponding switches to select said plurality of trunk lines, and means operative when all of said trunk lines are busy for marking said trunk lines as busy in the predetermined contact sets of the nonoperated one or ones of said switches.

50. In an automatic telephone system, a plurality of trunk lines, a plurality of automatic switches having corresponding sets of contacts adapted to be connected to lines outgoing from said switches, each of said switches having access to all of said trunk lines over a single predetermined set of contacts which corresponds to the predetermined contact set in each of the other switches, a plurality of sets of relays individual to certain of said switches and each including relays individually corresponding to said trunk lines, each of said relays being operative to complete a connection between the corresponding trunk line and the predetermined contact set of the corresponding switch, additional relays individually corresponding to said trunk lines and each operative in response to the operation of a corresponding relay in any one of said relay sets, and means responsive to the operation of one of said additional relays for conditioning corresponding relays of said relay sets which correspond to an idle one of said trunk lines to operate in response to operation of the respective corresponding switches to select said plurality of trunk lines.

51. In an automatic telephone system, a plurality of trunk lines, a plurality of automatic switches having corresponding sets of contacts adapted to be connected to lines outgoing from said switches, each of said switches having access to all of said trunk lines over a single predetermined set of contacts which corresponds to the predetermined contact set in each of the other switches, a plurality of sets of relays individual to certain of said switches and each including relays individually corresponding to said trunk lines, each of said relays being operative to complete a connection between the corresponding trunk line and the predetermined contact set of the corresponding switch, additional

relays individually corresponding to said trunk lines and each operative in response to the operation of a corresponding relay in any one of said relay sets, means responsive to the operation of one of said additional relays for conditioning corresponding relays of said relay sets which correspond to an idle one of said trunk lines to operate in response to operation of the respective corresponding switches to select said plurality of trunk lines, and an all-trunks-busy relay operative to mark said trunk lines as busy in the predetermined contacts sets of the nonoperated one or ones of said switches when all of said additional relays are operated.

52. In a telephone system, a plurality of lines, means including an automatic switch for routing a connection from a calling one of said lines to a called one of said lines, a source of ringing current, said switch comprising means including a ringing relay for repeatedly connecting said called line to said source, and means responsive to the first operation of said relay for completing a talking circuit between said lines.

53. In a telephone system, a plurality of lines, means including an automatic switch for routing a connection from a calling one of said lines to a called one of said lines, a source of ringing current, said switch comprising means including a ringing relay for repeatedly connecting said called line to said source, and means responsive to the first operation of said relay for completing a talking circuit between said lines and for completing a circuit including said source for transmitting ringing current over said calling line.

54. In a telephone system, a plurality of lines, an operator's position, a calling device at said operator's position, means including a finder switch for extending a connection to said operator's position, an automatic switch operative to extend said connection to a called one of said lines in response to operation of said calling device, a source of ringing current, a ringing control relay operative in response to operation of said calling device to connect said called line to said source for variable time intervals determined by the operation of said calling device, and means responsive to the first operation of said relay for completing a talking circuit between said lines.

55. In a telephone system, a plurality of lines, an operator's position, a calling device at said operator's position, means including a finder switch for extending a connection from a calling one of said lines to said operator's position, an automatic switch operative to extend said connection to a called one of said lines in response to operation of said calling device, a source of ringing current, a ringing control relay operative in response to operation of said calling device to connect said called line to said source for variable time intervals determined by the operation of said calling device, and means responsive to the first operation of said relay for completing a talking circuit between said lines and for completing a circuit including said source for transmitting ringing current over said calling line.

56. In a telephone system, a plurality of lines, an operator's position, an automatic switch having a trunk line extending to said switch, said switch having a normal position and being operative to any one of a plurality of off-normal positions to select one of said lines, and means responsive to the initiation of a call on said trunk line for impressing a signal voltage on said trunk

line only if said switch occupies its normal position.

57. In a telephone system, a plurality of lines, an operator's position, an automatic switch having a trunk line extending to said switch, said switch having a normal position and being operative to any one of a plurality of off-normal positions to select one of said lines, a signaling circuit including said trunk line, and means responsive to the initiation of a call on said trunk line for closing a point in said circuit, said circuit including one of the normal contacts of said switch whereby it is completed in response to operation of said last-named means only if said switch occupies its normal position.

58. In a telephone system, a plurality of lines, a finder-connector link including a finder switch and a connector switch each having access to said lines, said connector switch having a normal position and being operative to any one of a plurality of off-normal positions to select one of said lines, an operator's position, a trunk line extending from said link to said operator's position, a circuit including said trunk line for transmitting a signal to said operator's position, means responsive to the initiation of a call on said trunk line for completing said circuit only if said connector switch occupies its normal position, and means responsive to operation of said finder switch to seize a calling one of said lines for opening a point in said circuit.

59. In a telephone system, a plurality of lines, a finder-connector link including a finder switch and a connector switch each having access to said lines, said connector switch having a normal position and being operative to any one of a plurality of off-normal positions to select one of said lines, an operator's position, a trunk line extending from said link to said operator's position, a circuit including said trunk line for transmitting a signal to said operator's position, means responsive to the initiation of a call on said trunk line for closing a point in said circuit, said circuit including one of the normal contacts of said connector switch, whereby it is completed only if said connector switch occupies its normal position, and means responsive to operation of said finder switch to seize a calling one of said lines for opening a point in said circuit.

60. In a telephone system, an exchange including line connecting apparatus comprising a plurality of links and common equipment, an operator's position, a trunk line extending from one of said links to said operator's position, a plurality of lines extending to said exchange, said one link including a connector switch having a normal position and operative to a plurality of off-normal positions individually corresponding to said lines, said connector switch being controllable over said trunk line from said operator's position to extend a connection from a calling one of said lines to a called one of said lines, a circuit for transmitting signal current to said operator's position, means whereby said circuit is completed when a call is initiated on said trunk line only if said connector switch occupies its normal position, and means for normally energizing said circuit with current of one signaling characteristic and for energizing said circuit with current of a different signaling characteristic when a fault is present in said apparatus.

61. In a telephone system, a plurality of lines, at least one of said lines extending to a substation of the paystation type, a plurality of links each including a finder switch having access to

said line, a distributor operative to assign said links to the use of calling ones of said lines, a relay included in said distributor and operative to initiate operation of said distributor to select an idle link, an operator's position, and a circuit controlled by said relay for transmitting to said operator's position a signal identifying the character of said one line.

62. In a telephone system, a plurality of lines, at least one of said lines extending to a substation of the paystation type, a plurality of links each including a finder switch having access to said line, a distributor operative to assign said links to the use of calling ones of said lines, a relay included in said distributor and operative to initiate operation of said distributor to select an idle link, said distributor also including a start relay operative to initiate operation of an assigned finder switch to search for a calling one of said lines, an operator's position, and a circuit jointly controlled by said relays for transmitting to said operator's position a signal identifying the character of said one line.

63. In a telephone system, a calling line, a called line, means including a connector switch

for routing a connection from said calling line to said called line, said connector switch including means for determining the idle or busy condition of said called line and for transmitting a busy signal over the calling line if the called line is busy, and means operative to hold said connector switch operated, thereby to continue the transmission of said busy signal over said calling line, for a predetermined time interval after said connector switch is conditioned for release.

64. In an automatic telephone system, a plurality of trunks, automatic switches having corresponding sets of outlet contacts, and means for rendering all of said trunks accessible to each of said switches over a single predetermined set of outlet contacts in each of said switches.

65. In an automatic telephone system, a plurality of trunks, automatic switches having corresponding sets of outlet contacts, means for rendering all of said trunks accessible to each of said switches over a single predetermined set of outlet contacts in each of said switches, and means for allotting idle ones of said trunks for use in a predetermined order.

JOHN H. VOSS.
